[57] ABSTRACT

Apparatus for lining a metallurgical vessel (ladle) having a continuous arcuate rim by delivering wads of prepared refractory material having high kinetic energy into the arcuate space existing between the side wall of the vessel and a conformably shaped pattern in centered relation within the vessel. A turntable which rotates about the common axis of the vessel and the pattern carries an eccentrically disposed, radially shiftable, rotary, motor-driven slinger which is constrained to follow the contour of the rim during rotation of the turntable and, thus, maintain its discharge chute in register with the aforesaid arcuate space. A conveyor system receives the lining material from a nearby feeder and delivers a continuous flow thereof to the slinger. The pattern is expansible and contractible to facilitate its removal from the newly-lined vessel.

APPARATUS FOR LINING THE WALLS OF
METALLURGICAL VESSELS WITH PREPARED
REFRACTORY MATERIAL

The present invention relates generally to an apparatus for lining the side walls of metallurgical vessels such as steel mill pouring ladles and the like. More specifically, the invention is concerned with a fully automatic apparatus which is designed particularly for use in connection with the application of a homogenous monolithic lining which is comprised of prepared refractory material to the inner side wall surface of a relatively large generally cylindrical pouring ladle having a diameter of from 12 to 15 feet or more in the rim region thereof and having a depth up to 18 or more feet. Such a ladle has a pouring capacity in excess of 250 tons where the larger size ladles are concerned, the ladle itself weighing up to forty tons, and the refractory material of the liner which is installed therein weighing up to 26 tons.

Still more specifically, the invention is related to a ladle lining apparatus of the type that employs a rotary, motor-driven slinger for the purpose of filling the continuous arcuate space which exists between the side wall of the ladle and the outside surface or side wall of a pattern which initially is centered within the ladle, the slinger delivering small wads of prepared refractory material into the aforesaid space through the rim of the ladle so as progressively to build up the refractory liner, the pattern being lifted from the ladle after the liner is fully formed so as to leave the liner in position against the inner surface of the side wall of the ladle.

This type of apparatus represents a fairly recent innovation in the art of lining ladles, prior ladle lining apparatuses and methods being predicated upon the placement of preformed pieces of solid refractory material (usually firebrick) in position by hand and requiring the use of skilled masonry workers to perform the operation. The progressive building up of a lining within the arcuate space between the side wall of the ladle and the side wall of a pattern within the ladle as previously described by the use of a rotary, power-driven slinger which projects wads of the prepared refractory material into the space is currently being practiced by using either of two systems.

In one system, the pattern-equipped ladle is supported on a rotary turntable and the slinger is fixedly mounted in a position above the table so that its discharge chute registers with the arcuate space which is established between the ladle and the pattern. Such a system is not well adapted to accommodate or be practically used in connection with ladles having a holding capacity of only about one hundred tons and, therefore, the present invention which, as previously indicated, is designed for lining considerably larger ladles, is not particularly concerned with a rotary ladle lining system, although certain of the features thereof may possibly find application thereto.

In the other system, the pattern-equipped ladle remains stationary while the slinger is caused to revolve about the common axis of the ladle and the pattern and, during such movement of the slinger, its discharge chute is maintained in register with the arcuate space between the ladle side wall and the outer surface of the side wall of the pattern. It is to this latter type of ladle lining system that the present invention specifically relates. However, with either system, the arcuate space

becomes progressively built up by the rapid fire compacting of the prepared refractory material within said space, the wads of material initially being compacted with great force against the bottom portion of the space until it is covered, after which wads are compacted against previously compacted (rammed) lining material with the process being carried out throughout the entire ladle lining operation and until the ladle has been fully lined.

10 Although ladle lining apparatuses which are predicated upon the use of this latter system are currently well developed, the system itself is not without its limitations, and principal among these is the inability of the particular ladle lining apparatus to perform the ramming operation continuously since it is necessary to resort to ramming in no less than three stages, the first stage being performed with the presence of a relatively short pattern within the bottom portion of the ladle, each successive stage being performed after an additional pattern section has been placed upon an underlying pattern section. The reason for this is that with the semi-automatic ladle lining apparatus currently in use, it has not been possible in actual practice to "aim" the discharge chute of the rotary, motor-driven slinger into the arcuate space between the ladle side wall and the centered pattern within the ladle and maintain it properly aimed during revolution of the slinger about the common ladle and pattern axis with sufficient accuracy that the wads of refractory lining material can be directed downwardly throughout the full depth (up to 18 feet or more) of the arcuate space so that the high impact resulting from their high kinetic energy can be effective against the bottom of the aforesaid space instead of this energy being dissipated prematurely by contact of the wads with the side wall of either the ladle or the pattern. Since in steel mills which produce refined steels, the cost of ladle lining is an important cost factor, this shut-down time which is consumed during the effecting of pattern additions represents an appreciable idle time loss.

45 The present invention overcomes the above-noted limitation in that novel means are provided for accurately guiding the discharge chute of the rotary, power-driven slinger during its revolution about the axis of the ladle so that it is at all times in register with the liner-forming arcuate space and properly "aimed" with respect thereto regardless of whether this space is circular, elliptical or otherwise out-of-round, and regardless 50 of the mean slant angle of the space in the case of ladles which are of frusto-conical or elliptical design. The provision of this means for accurately guiding and aiming the discharge chute of the slinger constitutes one of the principal objects of the present invention, and in carrying out this object, the invention contemplates 55 that the discharge chute shall lie just outside of the rim of the pattern shell and be "aimed" so that it discharges its wads in precise parallelism with the pattern side wall, i.e., at the same angle as that of the side wall of the pattern. It is further contemplated that the width of the arcuate space shall be wider than the width of the wads which are discharged from the discharge chute of the slinger so that, regardless of fairly large departures 60 in the uniformity of the ladle side wall, as, for example, where the ladle is formed with a pouring lip, projection of the wads in an unhampered manner against the bottom of the progressively diminishing annulus is at all 65 times insured. Furthermore, by such an arrangement,

a given pattern is capable of serving ladles which vary in diameter within certain limits.

A further feature of the present invention resides in the provision of a novel mounting means for the rotary, motor-driven slinger, such means embodying a ramming unit which includes the slinger and rotates bodily about the common axis of the ladle and the pattern with the slinger being eccentrically mounted on the unit and freely slideable thereon radially under the control of the aforementioned guiding means for the discharge chute so that, in the case of a pattern having an elliptical rim, as the chute traverses a major axis of the ellipse, the slinger will assume a position of greater eccentricity than when the chute traverses a minor axis of the ellipse. Additional novel means are provided whereby the inclination of the discharge chute may be varied at will to attain the aforementioned condition of parallelism of wad discharge with the side wall of the pattern during ramming of the annulus.

Still another feature of the present invention, in one form thereof, resides in the provision of a novel means for conducting the prepared refractory lining material from a remote point where it is discharged from a feeder to the revolving hopper of the slinger in the vicinity of the ladle and pattern installation or assembly, such means embodying a composite, articulated, two-part conveyor having a receiving hopper permanently in receiving register with the fixed discharge chute of the feeder and having its discharge end permanently in discharging register with the circumferentially travelling receiving hopper of the revolving slinger, the medial region of such articulated conveyor being in the form of an elbow joint which flexes during the closed path movement of the rotary motor-driven slinger. By such an arrangement, a continuous flow of the prepared refractory material to the slinger is at all times assured.

A further serious limitation which is attendant upon the construction and use of conventional rotary, motor-driven slingers for the filling of the relative deep arcuate ladle-to-pattern spaces which are encountered in the lining of large ladles resides in the inability of such slingers to develop sufficient sand-compacting reaction force to create lining material wads of such adequate density as to create the necessary impact force to produce a homogenous and dense ladle lining that will not crumble or crack during pattern removal operations or when, after the usual drying operation has been performed, it comes into contact with molten metal. Heretofore, with conventional ladle lining apparatus employing a rotary, motor-driven slinger having a discharge chute which follows the elliptical or other path of the arcuate space undergoing ramming, the slinger which is used is generally a conventional "Sandslinger" of the well-known type wherein an impeller-mounted slinger cup, upon rotation thereof about a horizontal axis, picks up successively a measured quantity of conditioned sand, employs the impact force thereof to shape the sand into the form of a wad, and flings the wad by centrifugal force through a discharge outlet in the impeller casing and into the discharge chute of the slinger. Such a slinger invariably engages the measured quantity of sand at a 12 o'clock position as it is falling freely from the associated sand conveyor and discharges it at a 9 o'clock position, the impeller rotating in a counterclockwise direction. The initial impact between the cup and the freely falling measured quantity

of sand, together with the small 90° amplitude of movement of the filled cup before it discharges its contents in the 9 o'clock position, does not yield an adequate impact force properly to compact the sand into a sufficiently dense mass for proper ramming and there is some loose sand discharged along with each wad. The present invention overcomes this lack of wad density by providing a novel form of rotary, motor-driven slinger which is particularly well adapted for ladle lining use in that adequate refractory lining material is delivered continuously to the impeller casing in the bottom region thereof that the impeller cup effectively engages the material at the 6 o'clock position, then "plows into" such mass of material, so to speak, then picks up its full capacity of the lining material with impact force, and finally forces it around through the 12 o'clock position and discharges it at the 9 o'clock position. During this 270° sweep of the cup around the impeller casing, the refractory material has time to assimilate itself into the wad as the cup pushes it forwardly so that at the time it is flung from the casing at the 9 o'clock position an extremely dense and full wad is created which is better suited to meet the requirements of ramming procedures than are the wads of material which are delivered by conventional "sandslingers" when put to such use.

The efficiency of the present ladle lining apparatus over conventional or previously designed apparatus for the same purpose is further enhanced by numerous other features of novelty not specifically elaborated upon at this time but which will be described in detail subsequently. Among these are a novel pattern for the ladle, having facilities for centering the same in the ladle at the time it is initially installed therein and, thereafter, levelling the same within the ladle in order to bring the axes of the pattern and ladle into coincidence; having facilities for shrinking or contracting the same after the refractory lining has been completed within the arcuate space surrounding the pattern so as to break the bond between the latter and the green lining material in order that the pattern may be hoisted from the lined ladle; and also having facilities for guiding the ramming unit or slinger as a whole into an axially centered and operative position above the rim of the ladle and thereafter supporting such assembly during ladle-lining operations. A further feature of novelty which is associated with the pattern per se resides in the provision of means for confining the prepared refractory material which is rammed into the arcuate ladle-to-pattern space and preventing the same from flowing inwardly over the bottom wall of the ladle.

In general, the principal object of the invention is to provide a ladle-lining apparatus which is generally of new and improved construction, effectively and efficiently performs its intended purpose, and embodies a novel and improved arrangement of parts.

The invention consists in the several novel features which are hereinafter set forth and are more particularly defined by the claims at the conclusion hereof.

In the accompanying drawings, two embodiments of the invention are illustrated. In one embodiment, the rotatable ramming unit or slinger is center-fed, which is to say that the prepared refractory material is discharged into a centrally-located hopper which is coaxial with the common axis of the ladle and pattern assembly and from which this material is conveyor-fed radially outwards and discharged into the receiving

hopper of the eccentrically mounted orbiting slinger for wad-distribution into the arcuate space between the side walls of the ladle and the pattern. In the other embodiment, the ramming unit or slinger is peripherally fed, which is to say that the prepared refractory material is discharged directly into the receiving hopper of the orbiting slinger. However, in each of these embodiments of the invention, substantially all of the above-outlined advantages of the invention are prevalent and the structural components which make such advantages possible are preserved, substantially without modification. For example, in either embodiment of the invention, the pattern and its associated aligning and centering mechanism, the ramming unit and its associated rotary, motor-driven slinger, at least portions of the conveyor structure by means of which the refractory material is conducted to the orbiting sand slinger, and the sand treating or preparation components by means of which the raw batches of dry refractory material is conditioned and fed to the ramming unit or slinger in a continuous flow, remain substantially the same.

These two embodiments of the invention are illustrated in the accompanying twelve sheets of drawings which form a part of this specification.

In these drawings:

FIG. 1 is a top plan view, somewhat schematic in its representation, showing a steel mill installation which incorporates one embodiment of a ladle-lining apparatus embodying the present invention;

FIG. 2 is a side elevational view, partly in section, of the installation which is illustrated in FIG. 1;

FIG. 3 is a fragmentary side elevational view, partly in section and on an enlarged scale, of a portion of the structure which is shown in FIG. 2, the view showing the details of a particular sand-receiving conveyor which is employed in connection with and forms part of the invention;

FIG. 4 is a fragmentary top plan view of the structure which is shown in FIG. 3;

FIG. 5 is a fragmentary side elevational view, partly in section and on an enlarged scale, of a portion of the structure which is shown in FIG. 2, the view illustrating the details of a terminal sand delivery conveyor which is employed in connection with the invention;

FIG. 6 is a plan view of the structure which is shown in FIG. 5;

FIG. 7 is an enlarged vertical transverse sectional view taken on the line 7-7 of FIG. 3;

FIG. 8 is an enlarged vertical transverse sectional view taken on the line 8-8 of FIG. 3;

FIG. 9 is an enlarged vertical transverse sectional view taken on the line 9-9 of FIG. 3;

FIG. 10 is an enlarged vertical transverse sectional view taken on the line 10-10 of FIG. 3;

FIG. 11 is a top plan view of a complete ramming unit or rotary, motor-driven slinger and its associated drive mechanism, this view being taken on an enlarged scale and in the direction of the arrows which are associated with the line 11-11 of FIG. 2;

FIG. 12 is a fragmentary side elevational view of the structure which is shown in FIG. 11;

FIG. 12a is a vertical transverse sectional view taken on the line 12a-12a of FIG. 12;

FIG. 13 is an enlarged vertical longitudinal sectional view of the various parts which are illustrated in the right-hand portion of FIG. 11;

FIG. 14 is a vertical transverse sectional view taken on the line 14-14 of FIG. 13;

FIG. 15 is a view, partly in elevation and partly in vertical section, of the mounting structure for the ramming unit or slinger or the ladle-lining apparatus of FIG. 1;

FIG. 16 is an enlarged fragmentary horizontal sectional view taken on the line 16-16 of FIG. 15;

FIG. 17 is a fragmentary top plan view looking downwardly into the pattern shell assembly which is employed in connection with the present invention;

FIG. 17a is an enlarged fragmentary detail top plan view of the gate structure which is shown in FIG. 17, the gate proper being shown in an open position;

FIG. 18 is a vertical sectional view taken on the line 18-18 of FIG. 17;

FIG. 19 is a vertical sectional view taken on the line 19-19 of FIG. 17;

FIG. 20 is a vertical sectional view taken on the line 20-20 of FIG. 17;

FIG. 21 is an enlarged fragmentary side elevational view of a portion of the structure which is shown in FIGS. 17 and 19, the view disclosing the details of one of a number of spreader jacks which are associated with the pattern shell assembly of the apparatus;

FIG. 22 is an enlarged fragmentary detail view of the structure which is enclosed in the dotted line circle F22 of FIG. 19;

FIG. 23 is an enlarged fragmentary detail view of the structure which is enclosed in the dotted line circle F23 of FIG. 19;

FIG. 24 is an enlarged fragmentary detail view of the structure which is enclosed in the dotted line circle F24 of FIG. 19;

FIG. 25 is a reduced fragmentary horizontal sectional view taken on the line 25-25 of FIG. 20 and showing the details of a gate mechanism which is employed in connection with the invention, the gate proper being illustrated in its closed position;

FIG. 26 is a sectional view similar to FIG. 25 but showing the gate proper in its open position;

FIG. 27 is a reduced fragmentary horizontal sectional view similar to FIG. 25 but showing the details of another and counterpart gate mechanism which is employed in connection with the present invention, the gate proper being shown in its closed position;

FIG. 28 is a sectional view similar to FIG. 27 but showing the gate proper in its open position;

FIG. 29 is a horizontal view taken through the bottom portion of FIG. 19 and illustrating the nature of the pattern shell centering mechanism which is employed in connection with the invention;

FIG. 30 is an enlarged vertical sectional view taken on the line 30-30 of FIG. 29;

FIG. 31 is an enlarged vertical sectional view taken on the line 31-31 of FIG. 29;

FIG. 32 is an enlarged vertical sectional view taken on the line 32-32 of FIG. 29;

FIG. 33 is an enlarged vertical sectional view taken on the line 33-33 of FIG. 29; and

FIG. 34 is a side elevational view, partly in section, illustrating a modified and center feed arrangement for the ramming unit or slinger which is employed in connection with the installation of FIGS. 1 to 33, inclusive.

Referring now to the drawings in detail and in particular to FIGS. 1 and 2 wherein a complete steel mill ladle-lining installation or system is illustrated in a somewhat diagrammatic fashion, a metallurgical vessel in

the form of a pouring ladle for molten steel is designated in its entirety by the reference numeral 10, a ladle being operatively positioned in a ladle pit 12 where the ladle-lining procedure takes place. The upper portion of the ladle 10 is provided with the usual outwardly extending, diametrically opposite supporting trunnions 14 by means of which it is supported when, after lining, it is used in connection with an overhead hoist for actual metal pouring operations. The trunnions 14 are secured in thickened bosses 15. As shown in FIG. 2, the ladle 10 comprises a circular bottom wall 16 and a continuous side wall 18 which terminates in an open or exposed upper rim 20. The latter in the illustrated form of ladle, is generally oval or elliptical but may under certain circumstances be truly circular. If desired, the side wall may be provided with the usual thin safety liner, but such a liner is not shown in the drawings in the interest of clarity. The bosses 15 are formed as integral parts of the upper portion of the side wall 18. The ladle-lining apparatus of the present invention is capable of use, without any modification whatsoever, for lining metallurgical vessels regardless of whether the same present either circular or elliptical rims. The ladle pit 12 exists by reason of a concrete pit-forming shell 22 which is shown as being positioned in a conformably-shaped opening 24 in the floor or foundation surface 26 of the steel mill. Spaced apart, horizontally extending, channel beams 28 extend along a pair of opposed sides of the pit-forming shell 22 and receive thereon the trunnion-supporting bosses 15 in ladle-supporting relationship.

In FIGS. 1 and 2 of the drawings, the ladle 10 is shown in its ladle-lining environment, i.e., in associated relationship with the ladle-lining apparatus of the present invention and in its fully lined condition at the termination of the ladle-lining operation but prior to dismantlement and withdrawal of the liner pattern of the apparatus from the interior of the ladle. In these figures, the completely installed lining or liner is shown at 30, and it is in the nature of a homogenous monolithic mass which is formed of compacted wads of prepared refractory material and then cured by a firing operation as well known in the art. The liner 30 is generally of frusto-conical or elliptical configuration and is formed by progressively introducing wads of the lining material into the arcuate space 32 which exists between the inner face of the side wall 18 of the ladle 10 and the outer side face of the aforementioned liner pattern. The latter is designated by the reference numeral 31 and is removably disposed within the ladle 10 in centered relationship. As will be described in detail subsequently, the liner-forming pattern 34 is of a sectional composite nature and it includes a four-part split pattern wall or shell 36 of a generally frusto-conical or elliptical configuration which is conformable in shape to the frusto-conical or elliptical configuration of the ladle side wall 18 but which is of lesser radial extent so that when the pattern shell is centered within the ladle 10, the aforementioned arcuate space 32 is established. For convenience, such space will hereafter be referred to as an "annulus."

In order to break the bond between the formed refractory liner 30 and the liner pattern 34 after the ladle 10 has been lined, the pattern shell 36 is capable of limited contraction. After such contraction of the pattern shell, the pattern 34 as a whole may be hoisted by an overhead hoist or crane (not shown) from its centered

relationship within the ladle 10. This liner pattern constitutes one of the principal features of the present invention and it has associated therewith novel internal means for contracting its shell 36, as well as means whereby the liner pattern as a whole may be hoisted into position within the ladle 10 and removed therefrom. Such means have been omitted from FIGS. 1 and 2 in the interest of clarity but they appear elsewhere in the drawings.

Still referring to FIGS. 1 and 2, the lining material which ultimately is delivered to the annulus 32 for ladle-lining purposes is in the form of a prepared refractory mix which is obtained in packaged form. This material is batch fed by a skip hoist 38 to a conventional mulling apparatus such as is illustrated schematically in FIGS. 1 and 2 and is designated in its entirety by the reference numeral 40. The apparatus 40 forms no part of the present invention and, therefore, the details thereof have not been disclosed herein. Suffice it to say, such apparatus is of the top feed open rim type and includes a mulling bowl 42 within which there is a rotary, power-driven crosshead having mounted thereon a series of plows which serve to agitate, squeeze, and aerate the refractory mix while at the same time water in predetermined quantity is introduced into the bowl 42. The aforementioned refractory mix consists of granular material to which there has been added suitable conditioning substances, the mix as a whole, however, being a "dry" mix requiring only the addition of, and intimate mixing with, a predetermined percentage of water in order to attain an earth-like consistency which constitutes the required mixture and is suitable for introduction into the annulus 32 which exists between the pattern shell 36 and the side wall 18 of the ladle 10.

As will be described in detail subsequently, the refractory lining material which is introduced into the annulus 32 is delivered in the form of small wads which are flung from a slinger assembly 44 which constitutes the principal or effective functional component of a rotary ramming unit 45, the latter being adapted to be positioned in seated relationship on the liner pattern 34 after the latter has been properly installed in the ladle 10. Upon rotation of the ramming unit 45 bodily about the vertical axis of the pattern 34, the slinger travels or orbits in a generally circular or elliptical path and is provided with a discharge chute 46 which remains at all times in register with the annulus 32 and discharges the wads of refractory material thereinto. These wads are possessed of high kinetic energy so that they become compacted in the annulus which gradually becomes filled with the refractory material. After the annulus has become filled with the refractory material, the ramming unit 45 is hoisted from the liner pattern 34 and, thereafter, the shell 36 of the pattern is contracted radially in order to free the same from the formed liner 30. Thereafter, the liner pattern 34 is hoisted from the pit-supported ladle which, in turn, is hoisted from the pit 12 so that a fresh stand-by unlined ladle may be placed in the pit preparatory to a succeeding ladle-lining operation.

It is essential for proper filling of the annulus 32 that the slinger assembly 44 deliver its refractory liner-forming material to the annulus at a uniform rate so that this material will build up uniformly during filling of the annulus, and thus, result in uniform density of the completed lining. Since the mulling apparatus 40 is

of the batch type, it is necessary that the periodic batch discharge from the apparatus 40 be converted into a substantially steady flow of material to the slinger assembly 44. For this purpose, a bucket elevator 50 is positioned to receive the periodic batch discharge from the mulling apparatus 40 and to elevate the same for introduction into a feeder 52 which discharges the material in a mixed condition continuously onto an articulated conveyor assembly 54, the latter leading from the feeder 52 to the slinger assembly 44 of the ramming unit 45. The conveyor assembly 54 is comprised of two independently power-driven conveyors including a material-receiving conveyor 56 and a material-delivery conveyor 58, the former receiving the refractory lining material from the feeder 52 and the latter delivering such material directly to the orbiting slinger assembly 44 of the rotating ramming unit 45. The mulling apparatus 40 and its associated skip hoist 38 and the feeder 52 and its associated bucket elevator 50 possess no novelty since these items, in the main, are purchased items and function only to translate the batch feed of the lining material to the mulling apparatus 40 into a continuous flow of such material from the mulling apparatus to the receiving conveyor 56. For this reason, the components 38, 40, 50 and 52 have been schematically illustrated in FIGS. 1 and 2 and the description thereof herein will be functional rather than structural.

The skip hoist 38 (see FIG. 2) embodies a vertically shiftable dump bucket 60 which is slidably mounted on a relatively tall framework 62 and is adapted to be shifted vertically in opposite directions under the control of a reversible motor M1 at the upper end of the framework 62. In its lowered position, the dump bucket 60 assumes the upright position in which it is shown in full lines in FIG. 2, in such upright position the bucket being disposed adjacent to the floor or foundation surface 26 where its open rim is conveniently accessible for loading purposes. As the dump bucket progresses upwardly, it encounters a cam 64 adjacent to the upper portion of the framework 62. As the result of engagement with such cam, the bucket 60 is caused to tilt and empty its contents by gravity into the open upper end of the bowl 42 of the mulling apparatus 40.

The mulling apparatus 40 is fixedly mounted on the upper end of a concrete pedestal 66 and in the medial regions of the bowl thereof there is provided a discharge gate 68 which is adapted to be opened near the end of each mulling cycle so that as the apparatus continues to function, the moist lining material becomes discharged onto a horizontally disposed conveyor 70 by means of which it is conducted to the receiving hopper 72 of the bucket elevator 50. The conveyor 70 is of the belt type and includes driving and driven belt rollers 74 and 76, an endless belt 78, and an electric driving motor M2 which is operatively connected to the driving roller 74 by a belt and pulley arrangement 80.

The discharge end of the conveyor 70 overlies the aforementioned receiving hopper 72 which is associated with the bucket elevator 50 and the latter involves in its general organization the usual endless chain and bucket structure 82 which serves to conduct the lining material from the hopper 72 to the upper end of a surrounding, upstanding, rectangular, hollow casing 84 and deposit the same in a discharge chute 86. The latter empties into a receiving hopper 88 which is associated with the feeder 52. The chain and bucket

structure 82 is adapted to be driven under the control of an electric motor M3.

The feeder 52 is supported on an elevated platform 90 which is mounted on the bucket elevator casing 84 and includes a centrally fed, horizontally disposed, rotatable, material-receiving disk 91. The latter discharges the lining material which is received thereon in peripheral fashion and under the influence of one or more fixed scraper plates 92 which extend in secant fashion over the surface of the rotating disk 91. The peripherally-discharged lining material falls by gravity into a receiving hopper 94 which is associated with the aforementioned material-receiving conveyor 56.

Referring now additionally to FIGS. 3 and 4, the material-receiving conveyor 56 which constitutes a section of the articulated conveyor assembly 54 is, in the main, supported on a concrete pedestal 100 on the steel mill floor 26 and it includes a hollow, cast metal, tubular base 102 which is suitably anchored on the upper end of the pedestal 100 and has mounted on its upper end by means of bolts 104 (see FIG. 3) the inner tubular member 106 of a hinge assembly 108. The outer tubular member 110 of the hinge assembly 108 is freely and rotatably supported on the inner tubular member 106 by upper and lower roller bearings 112 and 114.

As best illustrated in FIGS. 3 and 7, the hinge assembly 108 constitutes a turret structure from which there projects radially outwards an elongated tubular conveyor beam 116, the latter having its inner or proximate end telescopically received and anchored in a tubular sleeve 118 which is formed integrally with and projects radially outwards from the outer tubular member 110 of the hinge assembly 108. A flat, plate-like stiffner web 120 extends lengthwise of the beam 116, is welded as indicated at 122 to said beam, projects vertically upwards, and has its proximate end fixedly secured to the outer tubular member 110 by means of a brace casting 124. The latter is secured by bolts 125 (see FIG. 7) to a boss 126 (see FIG. 3) which forms an external part of the outer tubular member 110 of the hinge assembly 108. The brace casting 124 is formed with an outwardly projecting web 127 having formed therein a slot 128 into which the proximate end of the stiffner web 120 extends and in which it is welded as indicated at 130.

The outer tubular member 110 of the hinge assembly 110 is provided at its upper end with a cap member 131 (see FIGS. 3 and 7) and it has an offset portion 132 to which a gearbox 133 is secured by bolts 134. An electric motor M4 is secured by bolts 136 to the gearbox 133 in driving relationship. The gearbox embodies internal gearing 137 (see FIG. 9) and is provided with a horizontal tubular output shaft 138 on which there is fixedly mounted a drive pulley 140 for an endless conveyor belt 142. A driven pulley 144 (see FIG. 3) for the belt 142 is carried at the distal end of an upper conveyor frame 146, the distal end of the latter being adjustably supported from the distal end region of the conveyor beam 116 in a manner that will be made clear presently.

The conveyor frame 146 forms part of the receiving conveyor 56 and is comprised of two parallel side bars 150 (see FIGS. 3, 4 and 7) which are formed from tube stock, the inner or proximate ends of these side bars being secured by a unitary U-shaped hinge bracket 151 (see also FIG. 9) to a fixed, horizontally extending sup-

porting shaft 152 which has one end thereof projecting through the gearbox 133 and connected fixedly thereto. The shaft 152 extends through and serves rotatably to support the aforementioned tubular output shaft 138. The hinge bracket 151 includes a pair of parallel side arms 153 (see FIG. 4) and an interconnecting bight portion 154, the outer ends of the side arms being pivotally attached to the fixedly mounted supporting shaft 152 by saddle connections 155 (see also FIG. 4). The bight portion 154 of the hinge bracket 151 is formed with a pair of upright saddles 156 (see FIGS. 3, 4 and 7) and the proximate ends of the side bars of the conveyor frame 146 are maintained firmly or rigidly seated in the saddles 156 by U-clamp assemblies 157. A connection 159 (see FIG. 7) leads to the interior of the rotatable output shaft 138 and serves to supply oil thereto for lubricating purposes.

The two parallel side bars 150 of the conveyor frame 146 are maintained in their spaced apart relationship by a series of three transversely extending struts 158 (see FIG. 3) having at the ends thereof downwardly extending flanges 160 which are secured by bolts 162 to the bars 150. These struts 158 serve to support therebetween a longitudinally extending dust shield 164 for the lower return reach of the endless conveyor belt 142 of the receiving conveyor 56. Angular stiffener bars 166 (see FIGS. 3, 4 and 8) overlie and are welded to the two side bars 150 of the conveyor frame 146 and are coextensive with a major portion of these side bars. The distal or outer end regions of the two side bars 150 are supported from the underlying conveyor beam 116 by means of a pair of upwardly extending and outwardly diverging supports 168 (see FIGS. 3 and 10) which have their upper ends secured to the bars 150 by means of U-clamp assemblies 170 and their lower ends secured to a split clamping block 172, the latter being adjustably clamped on the beam 116 by clamping bolts for longitudinal adjustment therealong. The effective height of the two upwardly extending and diverging supports 168 is somewhat greater than the effective distance between the proximate ends of the conveyor beam 116 and the conveyor frame 146 in order that in any adjusted position of the supports 168, said conveyor frame is possessed of slight inclination in a direction leading away from the conveyor-supporting gearbox 133. By shifting the positions of the supports 168 longitudinally in one direction or the other, the effective inclination of the upper conveyor frame 146 of the receiving conveyor assembly 58 may be varied within small limits.

Each of the three transverse struts 158 (see FIGS. 7 and 10) in addition to the strengthening function which it performs with respect to the conveyor frame 146 as a whole also constitutes a reaction support for the upper reach of the endless conveyor belt 142. Accordingly, each strut 158 serves as a support for a flat, longitudinally extending belt-supporting plate 174. The latter has depending adjustment studs 176 which threadedly receive thereon pairs of clamping nuts 178 by means of which the height of the plate 174 may be varied and the plate levelled when required. Longitudinally extending angle bars 180 are suitably secured to the side margins of the belt-supporting plate 174 and support the longitudinal edges of the endless conveyor belt 142. These angle bars also serve to contain the refractory lining material on the upper reach of the conveyor belt 142 and, accordingly, they extend substan-

tially the full length of the conveyor frame 146 of which they constitute a part. These angle bars constitute, in effect, guide rails for slidably supporting the aforementioned receiving hopper 94, the latter being provided at its side portions with saddle-like guide shoes 182, each of which straddles the vertical leg of one of the angle bars 180 in sliding relationship. Upwardly extending and inclined coil springs 184 (see FIGS. 3 and 7) have their upper ends fixedly secured to the side portions of the hopper 90 and their lower ends secured to horizontally and outwardly extending attachment ears 186 on the side portions of the belt-supporting plate 174. The normal tendency is for the springs 184 yieldingly to urge the hopper 94 forwardly in the direction of travel of the upper reach of the endless conveyor belt 142 of the receiving conveyor assembly 56, the forward movement of the hopper being determined by a pair of stop lugs 188 (see FIG. 3) which are fixedly connected to the angle bars 180 and are adapted to be engaged by the outer or distal ends of guide shoes 182.

At the distal end of the conveyor frame 146, there is provided a conveyor belt-tightening mechanism 190 (see FIGS. 3 and 4) in the form of a pair of externally threaded extension rods 192 each of which is telescopically slidably within the distal end of one of the tubular side bars 150 and threadedly receives thereon a spanner nut 194, the latter bears against the adjacent circular end of the associated side bar. The outer ends of the extension rods 192 are in the form of circular eyes or bearings and serve to support therebetween a horizontal shaft 196 on which the aforementioned driven pulley 144 is rotatably mounted. A U-shaped belt scraper 198 has its end portions connected to the circular eyes or bearings on the outer ends of the extension rods 192 and serves further to insure proper delivery of lining material to the delivery conveyor 58.

As shown in FIGS. 1, 2 and 3, the receiving conveyor 56 of the articulated conveyor assembly 54 delivers its refractory lining material into a receiving hopper 294 which is associated with and forms a part of the delivery conveyor 58. This latter conveyor is similar in many respects to the receiving conveyor 56 and, therefore, in order to avoid needless repetition of description, similar reference numerals, but of a higher order, have been applied to those parts of the delivery conveyor 58 which correspond to similar parts of the receiving conveyor 56 as, for example, between the disclosure of FIGS. 5 and 6 on the one hand and FIGS. 3 and 4 on the other.

Whereas the receiving conveyor 56 has its supporting frame 146 effectively supported by way of the conveyor beam 122, the delivery conveyor 58 has its supporting frame 346 (see FIGS. 5 and 6) effectively supported by upwardly and outwardly inclined brace bars 368 which correspond in function to the upwardly and outwardly diverging supports 168 for the conveyor frame 146 of the receiving conveyor 56. These brace bars 368 have their inner or lower ends secured as indicated at 369 to a bracket 371 which is connected to and forms a part of a cap member 331. The latter constitutes an element of a hinge assembly 308 which corresponds in function to the hinge assembly 108. Whereas the corresponding hinge assembly 108 of the receiving conveyor 56 is mounted on the pedestal-supported casting 102, the hinge assembly 308 of the delivery conveyor 58 is mounted on the extremity of the distal end of the conveyor beam 116 (see FIGS. 3

and 5) by means of a split clamp arrangement 373. The cap member 331 of the hinge assembly 308 is provided with an offset portion 332 which is similar to the offset portion 132 of the cap member 131 of the hinge assembly 108, and the receiving end of the delivery conveyor 58 is supported on said offset portion 332 of the cap member 331 and includes a gearbox 333, an electric motor M5, a drive pulley 340, a hinge bracket 351, a hopper 294, and substantially all of the structural parts which are associated with the receiving end of the receiving conveyor 56 and have been previously described in detail.

Since the discharge end of the delivery conveyor 58 is obliged to follow the orbiting path of movement of the slinger assembly 44 about the axis $s-x$ (see FIG. 12) in order constantly to deliver the refractory lining material thereto, a receiving hopper 500 which is associated with and forms a part of the slinger assembly 44 is drivingly connected to the discharge end of the delivery conveyor 58 in a manner that will be described presently. Except for the provision of such a driving connection between the hopper 500 and the discharge end of the delivery conveyor, the remainder of said delivery conveyor 58 is, as previously pointed out, substantially the same as has been described in connection with the receiving conveyor 56.

The aforementioned driving connection between the hopper 500 and the discharge end of the delivery conveyor 58 is best shown in FIGS. 5, 13 and 14 of the drawings and is designated in its entirety by the reference numeral 381. This connection also serves as a height-adjusting means for the distal or discharge end of the delivery conveyor 58. This height-adjusting and driving connection 381 includes a vertically extending elevation screw 383 having a crank arm 385 at its upper end for screw-turning purposes. The screw 383 is threaded through an internally threaded collar 387 which is carried by the bight portion of a substantially horizontal U-shaped conveyor frame extension 389. The free ends of the leg portions of the U-shaped frame extension 389 are fixedly connected in any suitable manner to the distal ends of the tubular side bars 350 of the supporting frame 346 of the delivery conveyor 58. A pair of lock nuts 391 straddles the collar 387 and is provided for the purpose of locking the collar 387 in any selected position of adjustment with respect to the elevation screw 383. A torque arm 393 is secured to and extends radially from one of the lock nuts 391 and serves, when manually turned in one direction, to facilitate loosening and tightening on the two lock nuts. After loosening of the two lock nuts, turning of the elevation screw 383 in one direction or the other serves either upwardly or downwardly to adjust the discharge end of the delivery conveyor 58 with respect to the hopper 500. The lower end of the elevation screw 383 seats in a reaction cup 395 which is carried by the central portion of a horizontally extending strut 397. The latter is disposed within and extends diametrically across the hopper 500 and has its ends suitably secured to opposed side portions of said hopper. The reaction cup 395 is designed that it permits the elevation screw 383 to turn freely without, however, any vertical displacement with respect to the hopper 500. The elevation screw 363 functions in the manner of an eccentric crank arm to impart either circular or elliptical orbital movement to the discharge end of the delivery conveyor 58 depending upon the shape of the rim of the ladle being relined by the apparatus.

It will be apparent from the foregoing description of the composite articulated conveyor assembly 54 and reference to FIG. 1 of the drawings, that since the proximate or receiving end of the receiving conveyor 56 is mounted for swinging movement about the fixed common vertical axis of the pedestal 100 and the base 102, while the slinger assembly 44 follows the closed arcuate path which is provided for it by the rim of the pattern shell 36 of the pattern 34 as previously described, the hinge assembly 308 by means of which the two conveyors 56 and 58 are hingedly connected together constitutes, in effect, a flexible elbow joint which yields to accommodate such arcuate travel of the slinger assembly 44 during filling of the annulus 32 with the refractory lining material. Because the distal or discharge end of the receiving conveyor 56 is at all times in register with the hopper 294 of the delivery conveyor 58, there will always be, regardless of the angular disposition of such elbow joint, a continuous stream of the refractory lining material flowing from the sand feeder 52 to the slinger assembly 44 and, consequently, into the annulus 32 between the side wall 22 of the ladle 10 and the side wall of the pattern shell 36.

Considering now the nature of the ramming unit 45 of the slinger assembly 44 and referring particularly to FIGS. 2 and 11 to 16, inclusive, as previously stated, this ramming unit is adapted to be hoisted into a central position in centering relationship over the ladle 10 after the liner pattern 34 has been operatively installed and levelled in the ladle. The details of the liner pattern and its internal mechanism will be set forth in detail subsequently, but for an understanding of the ramming unit 45 and the manner in which it functions to ram wads of lining material into the annulus 32 which exists between the side walls of the pattern shell 36 and the ladle 10, it is sufficient to state that the ramming unit 45 seats upon a pair of horizontally disposed, coplanar, shelf-like deck plates 502 and 503 (see FIG. 25) which extend across the upper region of the liner pattern and are fixedly secured therein. It should be understood that the disclosure of FIG. 2 of the drawings is largely schematic in its representation and that, therefore, these deck plates 502 and 503 are the only internal functional components of the liner pattern which are illustrated, the remaining internal components being omitted in the interests of clarity, especially since they are disclosed in detail in FIGS. 17 to 22, inclusive.

Referring now particularly to FIGS. 11, 12, 12a, 15, 17 and 18, the ramming unit 45 involves in its general organization an undercarriage 504 (see particularly FIGS. 17 and 18) which constitutes a base support for the ramming unit as a whole and is adapted to be removably mounted on the deck plates 502 and 503 of the liner pattern 34. This undercarriage 504 is in the form of a framework consisting of structural steel members and including a quadrilaterally arranged series of four radially diverging, horizontally disposed frame legs 506 (see FIG. 17) each of which is comprised of two parallel, spaced apart, structural channel members 508, the channel faces of which oppose each other. Said channel members are maintained in their parallel spaced relationship by means of inner end bars 510, outer end bars 512, and intermediate crossbars 514. The inner ends of the frame legs 506 are disposed in close proximity to one another so that the four legs,

considered collectively, establish a symmetrical cross which, when seated on the deck plate 502 substantially spans the rim region of the pattern shell 36 in two directions. The outer end regions of adjacent frame legs 506 are connected together by diagonal braces 516, there being four such struts and each strut consisting of a length of angle iron.

The above described undercarriage 504 constitutes a permanent component of the ramming unit 45 and is adapted, along with the entire unit, to be bodily lowered into the pattern shell 34 in order properly to position the slinger assembly 44 and also to support the same in its proper relationship with respect to the annulus 32 for ladle-lining purposes. Accordingly, in order to insure proper centering of the undercarriage 504, vertically extending, upwardly tapered, locating brackets 518 are fixedly secured by bolts 520 to the deck plates 502 and 503 in the peripheral region of the pattern shell 36 and each bracket cooperates with a respective frame opening 522 near the outer end of a frame leg 506 in guiding the undercarriage to its final home position as it is being lowered into the rim region of the liner pattern 34. The undercarriage 504 is adapted to be removably anchored in position on the deck plates 502 and 503 by means of bolts 524 which are threaded into the upper end portions of the locating brackets 518 and serve to secure hold-down plates 526 in a clamped position with respect to the outer ends of the frame legs 506. By removing the bolts 524 and the hold-down plates 526, the undercarriage 504 may be separated from the liner pattern 34 by a hoisting operation. Apertured hoisting lugs 528 are located in circumferentially spaced regions of the undercarriage 504 and are connected to either the struts 516, or the outermost crossbars 514, or both.

The ramming unit 45 which is shown in dotted lines in FIG. 18 in its permanently supported position on the undercarriage 504, is illustrated in detail in FIGS. 11 and 12 and involves in its general organization the previously mentioned slinger assembly 44 with its discharge chute 46, and also an electric motor M7 (see FIGS. 11, 13 and 14) for operating the rotor of the slinger assembly, a rotatable articulated supporting carriage assembly 530, a turret 532 for supporting the carriage assembly 530, an electric turret motor M6 (see FIGS. 15, 16 and 18) for rotating the turret, and a gear reduction device 534.

As best shown in FIG. 5, a turret 532 is of irregular box-like configuration and includes a fixed turret casing 540 which is supported on a horizontal base plate 542 which, in turn, is fixedly mounted on the undercarriage 504. Intermediate shelf portions 544 within the confines of the turret casing 540 establish upper and lower compartments 546 and 548. Reinforcing webs 550 underlie and are connected to the shelf portions 544 and serve to strengthen the casing 540.

The upper compartment 546 in the casing 540 of the ramming unit 45 encloses or surrounds a vertical series of rotatable collector rings 552, the latter being electrically connected to the slinger motor M7. These collector rings 552 cooperate with fixed brush units 554 (see FIG. 16), which are connected to a suitable source of current through a power supply cable 556 (see FIG. 12) which passes through the usual ladle hole 558 in the bottom wall 16 of the ladle 10. A detachable connector 560 is interposed in the cable 556 in order that the sections of the cable may be separated at such time

as the ramming unit 45 is removed from the liner pattern 34 after a ladle-lining operation.

A rotatable turret turntable 562 (see FIG. 15) is disposed over and supported on the upper portion of the turret casing 540 and is secured by screws 564 to a ring gear 566 the outer surface of which is provided with an annular series of outwardly extending teeth and the inner surface of which constitutes an outer race for an annular series of ball bearings 568. An inner race 570 for the ball bearings 568 is secured by screws 572 to an upper, outwardly extending rim flange 574 on the upper portion of the turret casing 540.

The ring gear 566 (see FIG. 16) together with the turret turntable 562 is driven by means of a pinion 576 which is fixedly secured to the upper end of a vertical output shaft 578 forming a part of the aforementioned gear reduction device 534, the latter being secured by bolts 580 to a pair of parallel, spaced apart, inverted channel members 582 which seat respectively on plates 584, the latter being supported on the channel members 508 of the undercarriage 504. The gear reduction device 534 embodies a horizontal input shaft which has a pulley 586 mounted thereon. Such pulley constitutes an element of a conventional "Reeves" driving mechanism 588 which connects the electric motor M6 to the gear reduction device 534 in driving relationship. The drive mechanism 588 further includes the usual spring-loaded split pulley assembly 590 (see FIG. 16) and an endless V-belt 592, the pulley assembly 590 being mounted on the drive shaft 594 of the motor M6 and the V-belt being trained around the pulley assembly 590 and the pulley 586. The motor is secured by bolts 598 to a horizontally shiftable motor platform 600 which is slidably mounted on a rectangular base frame 602. The latter is secured by bolts 604 to a pair of parallel, spaced apart, inverted channel members 606 which bridge the distance between the adjacent channel members 508 of one of the frame legs 506. A hand wheel 608 is disposed exteriorly of the frame 602 and operates to turn a screw shaft 610 which is rotatably journaled in said frame 602 and is held against longitudinal shifting by a collar 612. The screw shaft 610 is threaded through a nut 614 which is mounted on the underneath side of the motor platform 600, the arrangement being such that turning of the worm shaft in either direction under the control of the hand wheel 608 will alter the gear ratio which is effective between the motor M6 and the gear reduction device 534 in the usual manner of a "Reeves" drive mechanism.

Referring now to FIGS. 11, 12, 15 and 16, and in particular to FIG. 15, the aforementioned turret turntable 562, which is secured to the ring gear 566, constitutes a closure plate for the upper end of the turret casing 540. An inverted, cup-shaped, gear cover 620 of sheet metal is fixedly mounted on the turntable 562 for rotation in unison therewith and is spaced upwardly therefrom by means of spacer lugs 622. Such gear cover 620 is provided with a large clearance opening 624 for a guide bracket 626 (see FIGS. 11, 12 and 15) which is fixedly mounted on a horizontal base plate 628, the latter in turn, being secured to the turret turntable 562.

The turntable 562 is provided with a centrally disposed depending post 630 (see FIG. 15) on which there is telescopically mounted an insulating sleeve 632 which carries the aforementioned collector rings 552. The stationary brush units 554 are mounted on posts 632 which project upwardly from a ring 636, the latter

being secured to the shelf portions 544 of the turret casing 540.

As best shown in FIGS. 12 and 15 of the drawings, the guide bracket 626 is provided with a central, horizontally extending bore 640 in which there is slidably disposed a horizontal tubular slinger support in the form of a relatively massive guide tube 642. The latter, as will be apparent presently, constitutes a radially shiftable support for a slinger carriage. It will be understood by reference to FIG. 15 that the undercarriage 504 of the ramming unit 45, the pedestal-like casing 540 for the turret turntable 562, the motor M6, and the gear reduction device 534 are fixed components, while the turntable 562, the guide bracket 628, and the guide tube 642 constitute a rotatable assembly of components, the axis of rotation being identified by the vertical broken line axis $x-x$ in FIGS. 12 and 15, such axis being coincident with the vertical axis of the casing 540. As will be described in detail subsequently, the slinger assembly 46, its drive motor M7, the discharge chute 46, and other slinger components are mounted for limited longitudinal sliding movement on the distal end region of the guide tube 642. The aforementioned vertical axis $x-x$ is also coincident with the common central vertical axis of the pattern shell 34 and the ladle 10 and, therefore, limited shifting movement of the sand slinger assembly 44 and its associated components of the guide tube 642 is provided in order that said assembly may follow the elliptical or other non-circular contour of the open rim 20 of the ladle 10 during actual ladle lining operations.

Referring now to FIGS. 11, 12 and 12a, and disregarding for the time being the specific nature of the slinger assembly 44, it is sufficient to state that this slinger assembly, together with its drive motor M7, and also the previously mentioned receiving hopper 500 which is associated therewith, are of known construction, the slinger motor and the hopper being secured together as a basic slinger unit. This unit is supported bodily for limited longitudinal sliding movement on the distal end region of the guide rod 642 by means of a shiftable slinger carriage which is designated in its entirety by the reference numeral 652 and is slidably mounted on a pair of fixed, horizontally extending guide rods 654 (see FIGS. 12 and 12a). The guide rods 654 are carried by a saddle 656 (see FIG. 12a) which is in the form of an inverted channel member, overlies the guide rod 642, and is secured thereto by radial struts 660 which are welded at their outer ends to the side flanges of the channel member-type saddle 656 and at their inner ends to the guide tube 642. The saddle 656 is thus movable bodily with the guide tube 642 when the latter is adjusted longitudinally through and with respect to the guide bracket 626. Upstanding end flanges 664 on the saddle serve to support therebetween the aforementioned guide rods 642 as the result of the ends of such tubes being suitably fixedly secured thereto. The carriage 652 is provided with a pair of horizontally extending, spaced apart guide sleeves 666 which encompass the guide rods 654 and, in combination with the entire carriage 652, are slidable longitudinally on these guide rods. Flexible bellows-like boots 668 encompass the normally exposed portions of the guide rods 654 on opposite ends of each guide sleeve 666 in protective relationship.

The carriage 652 of the slinger assembly 44 involves in its general organization a shallow U-shaped support

670 having generally triangular upstanding side flanges 672 which, at the high points, thereof, are formed with openings 674 for the reception therein of a pair of horizontally and outwardly extending trunnions 676. The latter are carried on a pair of upstanding side flanges 677 that are formed on a base plate 678 (see FIGS. 12 and 12a), the latter overlying the U-shaped support 670 and being secured to and serving to support the electric motor M7. L-shaped cradle brackets 680 at the four corners of the base plate 678 are secured in position by screws 682 and serve fixedly to connect the motor and the base plate. Triangular webs 686 are welded to the bottom surface of the U-shaped support 670 and the outer side portions of the guide sleeves 666 and serve fixedly to connect together these parts of the slinger carriage 652.

From the together description, it will be apparent that the motor M7, together with its base plate 678, is capable of limited tilting movement about the axis of the horizontally extending trunnions 676 and, in order that the motor axis, and consequently, the inclination of the slinger assembly 44 may be varied within limits to accommodate different ladles, the side walls of which flare upwards at different angles, U-shaped adjusting screws 688 are connected to and project upwardly from the support 670 and extend through holes (not shown) in the motor base plate 678. Adjusting nuts 690 are mounted on the upper ends of the screws 688, are disposed above and below the plate 678, and serve when manipulated by turning thereof in one direction or the other to vary the inclination of the base plate with respect to the support 670.

It has previously been stated that with different ladles 10, the angularity of the annulus 32, i.e., the slant angle thereof, may vary within small degrees. The purpose of the angularly adjustable base plate 678 for the motor M7 and its associated adjusting screws 688 and nuts 690 is to vary the inclination of the axis of the motor M7 which, in turn, will vary the angularity of the axis of the slinger assembly 44 to the end that the axis of the disclosure chute 46 may be made commensurate with the slant angle of the annulus with which it is in register and to which it discharges the wads of refractory lining material.

Inasmuch as the diameter of circular ladle rims, or the mean diameter of elliptical ladle rims, may vary, it is necessary that the horizontally extending guide tube 642 for the slinger assembly 44 be made adjustable to vary the effective length of such guide tube. For a ladle rim of relatively small mean diameter, the radial distance of the discharge chute 46 from the vertical axis $x-x$ (see FIGS. 12 and 15) of the turret 532 will be small. For a ladle rim of relatively large mean diameter, this radial distance will be correspondingly large. The necessary change in the effective length of the guide tube 642 is effected by adjusting the tube axially in the centrally disposed bore 640 in the guide bracket 626 in one direction or the other. Accordingly, in the interests of rigidity, two separate adjusting means for shifting the guide tube 642 axially are provided. One such adjusting means consists of a pair of horizontally extending, spaced apart threaded adjustment rods 692 (see FIGS. 11, 12 and 15) which are disposed on opposite sides of the inner end portion of the guide tube 642 and have, on their left-hand ends as viewed in FIGS. 11, 12 and 15, pairs of clamping nuts 694. The latter are disposed in straddled relation with the ends of a horizontal cross-

bar 696, the medial region of which is fixedly secured to the inner end of the guide tube 542. The right-hand ends of the threaded adjustment rods 692 are similarly provided with pairs of clamping nuts 698 which straddle oppositely extending lateral ears 700 on the guide bracket 626. Thus, by loosening the various pairs of nuts 694 and 698, the guide tube may be longitudinally adjusted in such a direction as to bring the discharge chute 46 of the slinger assembly 44 into register with the annulus 32 of the ladle undergoing ramming, after which the clamping nuts may again be tightened in order to maintain the guide tube 642 in its adjusted position.

The other adjusting means for the guide tube 642 consists of an additional pair of horizontally extending, spaced apart threaded adjustment rods 702 (see FIGS. 11 or 12) having pairs of clamping nuts 704 on their left-hand ends as viewed in said figures of the drawings. Said pairs of nuts are arranged in straddled relation with a pair of horizontally extending sleeves 706 through which the left-hand ends of the rods 702 extend loosely. The sleeves are carried on the ends of a horizontally extending angle bar 708 which, in turn, is fixedly mounted on the upper ends of a pair of upstanding channel members 710. The latter seat on and are suitably fixedly connected to the guide bracket 626. The adjustment rods 702 have on their right-hand ends pairs of clamping nuts 712 and they are arranged in straddled relation with the ends of two horizontally extending, spaced apart sleeve members 714. The latter are fixedly connected to the upper portions of a pair of upstanding, inwardly inclined side webs 716 which are suitably connected to the inner portion of the saddle 656. Adjustment of the guide tube 642 axially in either direction is accomplished by manipulating the pairs of clamping nuts 702 and 712 in a manner similar to the manipulation of the aforementioned pairs of clamping nuts 694 and 698. It will be understood that before any axial shifting of the guide tube 642 may be accomplished, it is necessary that all of the pairs of clamping nuts 694, 698, 702 and 712 must be loosened.

Still referring to FIGS. 11 and 12 of the drawings, the two sleeve members 714 serve to support a horizontally extending cross member 720 which is in the form of an anglepiece and on which there is mounted a suitable control cabinet 722. The latter is intended to contain the various valve devices, relay mechanisms, and such other electrical or mechanical instrumentalities as may be employed in connection with the operation of the ladle lining apparatus. It is to be noted at this point that since the illustrations of FIGS. 1 and 2 are largely schematic in their representation, the aforementioned control cabinet, as well as numerous other apparatus components which appear throughout the drawings, have, therefore, been omitted from FIGS. 1 and 2 in the interests of clarity.

The details of the slinger assembly 44 are somewhat schematically illustrated in FIGS. 13 and 14, and this is true of the previously described means whereby the adjacent discharge end of the delivery conveyor 58 is supported from the receiving hopper 500. The latter is comprised of three sections, namely, an upper rim section 730 the axis of which extends vertically, a lower cylindrical section 732, and an intermediate interconnecting section 734, the axes of the sections 732 and 734 being inclined and substantially co-incident. The lower section 732 communicates through a large open-

ing 736 leading to the interior of the slinger assembly 44 in the lower regions thereof.

A pivoted damper plate 738 which extends across the interior of the lower section 734 of the delivery hopper 500, is mounted on a horizontally extending rock shaft 740 at the upper portion of said lower section 734, and is counterbalanced by means of weights 742 which are mounted on the distal ends of a pair of side arms 744, the latter being secured to the ends of the rock shaft 740 and extending radially therefrom. The damper plate is thus gravitationally biased toward a closed position.

Considering now the slinger assembly 44 per se, and referring particularly to FIGS. 13 and 14 of the drawings, this assembly operates upon basic principles that have long been used in foundry practice whereby measured quantities of molding sand are moved and positioned into the circular path movement of a cup-like blade which, by reason of its orbital or rotary movement, makes impact with the stream of sand and thus compacts it into the form of wads which are then flung radially downwards from the slinger casing with considerable velocity into a subjacent flask which is to be rammed with molding sand. These wads of sand "pile up" so to speak on each other by what is known as a ramming action and the cavity in the flask becomes thus filled with sand and at a comparatively high degree of density. For an understanding of this principle of cavity-filling, reference may be had to U.S. Pat. No. 1,309,833, granted on July 15, 1919, and entitled "MOLDING APPARATUS."

The present slinger assembly 44 represents a modification of a conventional standard sand slinger currently in use, the modifications which have been effected being such that they enable the slinger assembly 44 to produce a denser wad of material for more effective ramming of a deep cavity such as the eighteen-foot deep annulus 32 of the illustrated ladle 10. It has been found that a conventional sand slinger does not in all cases satisfactorily meet the requirements of a ladle-lining apparatus, even when its discharge chute is guided around the rim of the annulus 32 and is adjustable to accommodate varying slant angles of different ladles undergoing lining.

The slinger assembly 44 includes an impeller casing 750 consisting of a circular back wall 752, a cylindrical side wall 754, and a front wall 756 in the form of a cover plate 758 which is connected by a hinge structure 760 to one of the side portions of the side wall 754 and is secured in its normal or operative position by a bolt 761. Upon removal of the bolt 761, the hinge structure 760 permits the cover plate to be swung into an open position (not shown) in order to provide access to the interior of the casing 750. The aforementioned sand-receiving opening 736 is provided in the front wall 756. The back wall 752 is in the form of a spool-shaped casting consisting of spaced apart front and rear circular flange-like parts with an annular series of sleeve-like members therebetween. The front flange-like part serves as a back wall of the impeller casing and the rear flange-like part serves as the front wall of the electric motor M7. An annular series of reinforcing fins 753 is provided on the back wall 752. The motor M7 is provided with a horizontal drive shaft 762 to which there is keyed the hub portion 763 of an impeller 764. The latter is disposed in the central portion of the casing 750 and has fixedly mounted on one portion of its pe-

iphery a cup-like blade unit 766 including a blade proper 768. The latter is in the form of a short channel-like section having triangular sides. The blade proper is secured by a dovetail connection 770 and also by bolts 772 to a base 774 which is mounted on an impeller shelf 776 forming a part of the rotary, motor-driven impeller 764. The cylindrical side wall 754 of the casing 750 is provided internally with an arcuate steel liner 778 which is interrupted as indicated at 780 to provide in the vicinity of the discharge chute 46 a discharge opening of approximately 60° extent. The upper end of the discharge chute communicates through a casing boss 782 with the interior of the casing 750. The blade unit 766, being eccentrically positioned on the impeller 754, is counterbalanced by a diametrically opposite weight 784 which is suitably mounted on the impeller 764 (see FIG. 13).

As clearly shown in FIG. 13 of the drawings, the lower cylindrical section 732 of the delivery hopper 500 communicates through the opening 736 in the front wall 756 of the impeller casing 750 with the extreme lower region of the interior of the casing with the result that as the blade unit 766 orbits about the axis of the impeller 764 in a counterclockwise direction as viewed in FIG. 14, the mass of refractory lining material which collects in such lower region of the interior of the impeller casing 750 is encountered by the blade unit at an approximate 6 o'clock position, the blade proper 768 gathering as much lining material as it is capable of holding and forcing the material ahead of it circumferentially around the casing liner 778. At such time as this gathered refractory lining material encounters the interrupted region 780 of the liner, it is flung by centrifugal force outwardly and downwardly into the discharge chute 46 in the form of a densified wad, the action being repetitive each time the blade unit 766 makes a complete revolution. Since the material is picked up at a six 0'clock position as previously set forth and then moves counterclockwise until it is discharged at a 9 o'clock position, it remains in contact with the blade unit 766 throughout a travel of approximately 270°, the relatively long period of intimate contact of the blade unit with the lining material adding appreciably to the final density of the downwardly ejected wad.

Because of the fact that the lower end of the discharge chute 46 remains at all times, during rotation of the ramming unit 45 as previously described, in register with the annulus 32 which exists between the ladle 10 and the liner pattern 34, these wads of refractory lining material are forcibly projected or flung into the annulus, and they, as a consequence, gradually build up within the annulus by a sequence of uniform wad placements. Because of the increased hardness of these wads due to the extension of the impacting time cycle, the wads are capable of being flung the entire vertical distance of the annulus with substantially no wad disintegration.

The nature of the liner-forming pattern 34 of the apparatus is disclosed in FIGS. 17 to 33, inclusive. The disclosure of this pattern in FIGS. 1 and 2 is entirely schematic, there being shown in such figures of the drawings only a simple frusto-conical shell or wall 36 with no facilities for collapsing the same in order to break the bond between the shell and the liner after a ladle-lining operation and preparatory to lifting the pattern from the lined ladle.

As best shown in FIGS. 19 and 20, the liner pattern 34 involves in its general organization two superimposed pattern sections in the form of an upper section 800 and a lower section 802. These sections are somewhat similar in their construction and are equipped with similar internal components whereby they are capable of being collapsed and expanded for pattern removal and installation purposes as previously mentioned. The upper pattern section 800 is provided with a split two-part frusto-conical wall consisting of wall parts 804 and 805 (see FIGS. 20 and 25), and the lower pattern section 802 is provided with a split, two-part frusto-conical wall consisting of wall parts 806 and 807 (see FIGS. 20 and 27). The small base rim 808 of the upper frusto-conical section 800 is substantially equal in diameter to the large base rim 810 of the lower frusto-conical section 802 in order that the former rim may seat on the latter rim as shown in FIG. 23 when the sections are assembled upon each other within the confines of the ladle 10. When the two pattern sections 800 and 802 are thus assembled, the four wall parts 804, 805, 806 and 807 establish the aforementioned composite over-all frusto-conical pattern shell 36.

It will be understood that the term "frusto-conical" as employed herein is not necessarily intended to imply the fact that the walls of the upper and lower pattern sections 800 and 802 are in the shape of true cone frustums. In the illustrated form of the liner pattern 34, the rim region of the upper pattern section 800 is elliptical and the major axis of the ellipse is slightly longer than the minor axis. The small base of the lower pattern section may be circular, in which case it will be understood that the herein termed "frusto-conical" walls will be slightly out-of-round and will progress from an ellipse at the upper end of the liner pattern to a circle at the lower end of the pattern. Therefore, in the remainder of the specification, and in the appended claims, the terms "frusto-conical," "cylindrical," and "circular," or such terms when coupled with the prefix "semi-" are intended to include the out-of-round condition described above.

Considering now only the lower pattern section 802 which includes the wall parts 806 and 807 as indicated in FIG. 20, these two parts are hingedly connected together in clamshell fashion and along a vertical axis by means of a piano-type hinge 816 (see also FIGS. 25 and 27). Preferably, but not necessarily, such hinge connection is disposed on the minor axis of the generally elliptical pattern structure. Diametrically across the lower pattern section 802 with respect to the hinge 816 is a gate assembly 818. The latter includes a narrow vertical wall section or gate 820 which is connected by a piano-type hinge 822 to the distal side margin of the wall part 806 and constitutes a swing-in panel which normally lies or coincides with the frusto-conical contour of the wall parts 806 and 807 when the lower pattern section 802 is fully expanded as shown in FIG. 27, but which swings inwardly and assumes the position shown in FIG. 28 in order to permit the wall parts 806 and 807 to move closer together to effect slight contraction of the lower pattern section 802 for pattern removal purposes after the ladle 10 has been fully lined.

In order to manipulate the gate 820 between its two extreme positions (closed and open), a manually operable turnbuckel-type expansion and contraction jack 824 is disposed within the confines of the lower pattern section 802 and is connected at its opposite ends to the

gate 820 and to a fixed reaction bracket 826 on the distal portion of the wall part 806. The jack 824 constitutes one of a number of similar jacks which are employed in connection with the liner pattern 34 and the nature of these jacks will be made clear presently.

Relative movement of the clamshell-like wall parts 806 and 807 of the lower pattern section 802 toward and away from each other to contact or expand said lower pattern section, as previously described, is accomplished under the control of a turnbuckle-type expansion and spreader jack 830, which is similar to the jack 824, the jack 830 being connected at its opposite ends to two fixed reaction brackets 832 and 834 which are associated with the lower pattern section 802 and are disposed on opposite sides of the hinge 816 but adjacent to the distal portions of said wall parts 806 and 807.

The lower pattern section 802 of the liner pattern 34 may be provided with a wide variety of internal wall reinforcing components, depending upon the specific size and shape of the section. In the illustrated form of this pattern section, the reinforcing components consist of various radial gusset-like webs 840, vertical angle bars 842, and the like requires any detailed description at this point. The various gusset-like webs 840 serve to support thereon a pair of coplanar deck plates 844 and 846 which are similar to the previously described upper deck plates 502 and 503 and are secured by bolts 847 to and supported on curved or arcuate, longitudinally extending angle bars 848 (see FIG. 23), such angle bars being welded as indicated at 850 to the wall parts 806 and 807. Upstanding, apertured hoisting lugs 851 (see FIG. 20) are welded or otherwise fixedly secured to the deck plates 844 and 846.

The lower rim of the lower pattern section 802 is open and has installed therein a centering mechanism, a pattern levelling means, and a shield arrangement, the details of which are shown in FIGS. 29 to 32, inclusive, and the nature of which will be set forth presently.

Considering now the upper pattern section 800 of the liner pattern 34, except for its larger over-all mean diameter and a slightly different arrangement of the internal wall-reinforcing components which are associated therewith, this section is similar in its general organization to the lower pattern section 802 and, therefore, for descriptive purposes, it is deemed sufficient to designate the corresponding structural reinforcing components, for example, such as the gusset-like webs, the angle bars and the like, as well as the functional components including the gate assembly, the spreader jack for the clamshell-type wall parts 804 and 805, the hinge connections, and the turnbuckle-type expansion and contraction jack for the operation of the gate with identical reference numerals, and to describe such additional components as are present in connection with the upper pattern section 800.

Whereas the lower rim of the lower pattern section 802 is open as previously set forth, the lower rim of the upper pattern section 800 is provided with a pair of coplanar base plates 852 and 854 (see FIGS. 19 and 20) which seat respectively upon the deck plates 844 and 846 when the upper pattern section 800 is seated upon the lower pattern section 802. Clamping bolts 856 (see FIGS. 19 and 23) serve releasably to fasten the thus paired plates together and these bolts constitute the sole means whereby the two pattern sections may be

clamped to each other in order to provide a unitary pattern structure.

It is to be noted that the deck plates 502 and 503 which are rigidly secured within the upper portion of the upper pattern section 800 and serve to support the undercarriage 504 of the ramming unit 45 define therebetween a generally rectilinear opening 858 (see FIG. 25) this opening constituting a manhole by means of which a workman may descend below the deck plates 502 and 503. In order to facilitate the workman's descent, a ladder 860 extends between the deck plate 503 and the base plate 854 in the vicinity of this opening and is welded in position therebetween. The deck plates 844 and 846 of the lower pattern section 802 define therebetween a generally circular opening 862 (see FIG. 27) which constitutes a second manhole whereby a workman may descend below the deck plates 844 and 846, a second ladder 864 being welded to and suspended from the deck plate 846.

20 It will be understood that the hinges 816 and the gate assemblies 818 of the two superimposed pattern sections 800 and 802 are arranged in precise vertical alignment for operation in unison when the liner pattern 34 as a whole is expanded or collapsed.

25 The aforementioned turnbuckle-type jacks 830 (see FIGS. 19 and 20) and the turnbuckle-type jacks 824 (see FIGS. 25 and 27) are, except for size, substantially identical in construction, the spreader jacks for the clamshell pattern sections being larger than the manipulating jacks for the gate assemblies. One of the spreader jacks 830 is shown in detail in FIG. 21 and it includes an elongated turnbuckle sleeve 870 having internal threads which are of opposite pitch and cooperate with a pair of aligned spreader screws 872. The latter are provided at their outer ends with eyelets 873 by means of which they may be pivotally connected by lug and pivot pin arrangements to the parts which are to be spread apart or drawn together. A ratchet wheel 874 which is affixed to the central region of the sleeve 870 is adapted to be progressively manipulated by means of a spring-biased pawl 876 which is carried between the tines of a fork 878. The latter is pivotally connected to the central portion of the sleeve 870 and has a handle section 880 for manipulating purposes. The pawl 876 is of the double-acting type and may be set for cooperation with the ratchet wheel 874 to advance the latter in either rotational direction.

30 Means are provided for causing the discharge chute 46 of the slinger assembly 44 to remain in operative register with the annulus 32 between the side walls of the ladle 10 and the liner pattern 34 at all times during rotation of the ramming unit 45 about its vertical axis. Accordingly, and as best shown in FIGS. 19 and 24, the upper rim region of the upper pattern section 800 of 35 the liner pattern 34 is provided with a pair of arcuate hardened steel, chute-guiding rails 882 and 884, each rail being of approximately 180° extent. These rails are removably mounted on the upper rim of the upper pattern section 800, the rail 882 resting on the upper edge of the wall part 804 and the rail 884 resting on the upper edge of the wall part 805. Certain adjacent ends of the rails 882 and 884 abut each other along the vertical line of the hinge 816 of the upper pattern section 800. Diametrically across the upper pattern section 800 from the hinge 816, the other pair of adjacent ends of the rails 882 and 884 abut each other when the upper pattern section is in its expanded condition,

these latter abutting rail ends being disposed in the vicinity of the uppermost gate assembly 818 and in close proximity to the uppermost gate 820 which, at this time, is "closed." After "opening" of said uppermost gate 820 under the control of the associated turnbuckle-type jack 824, subsequent movement of the two clamshell-like wall parts 804 and 805 of the upper pattern section 800 toward each other by way of manipulation of the uppermost turnbuckle-type jack 830 will cause the last mentioned adjacent ends of the rails 882 and 884 to overlap each other as shown in FIG. 17a. This overlapping of the rail ends is initiated by reason of the fact that the meeting edges of said rail ends are bevelled in the same direction.

The two arcuate rails 882 and 884 are removably mounted on the upper edges of their respective wall parts 802 and 804 by means of an annular series of pilot lugs 890 (see FIGS. 18, 19 and 24) which are secured by bolts 892 to the upper margins of said wall parts on the inner sides thereof and project upwardly beyond the upper rim of the upper pattern section 800. Spacer plates 894 are interposed between the pilot lugs and the upper margins of the adjacent wall parts in order to attain the necessary inward offset of the pilot lugs 890 for proper downward piloting of the two rails 882 and 884 onto the rim of the upper pattern section 800. The rails thus constitute, in effect, an upper rim extension of the pattern shell.

As best illustrated in FIG. 12, the two arcuate rails 882 and 884 are designed for cooperation with a rail follower in the form of two spaced apart follower inner and outer rollers 896 which are carried on the lower end of a vertically adjustable, screw-threaded, stem-like support 898. The latter is adjustable by means of upper and lower clamping nuts 900 which are arranged in straddle relation with a shelf-like part of a supporting bracket 902, the latter being secured to the front end flange 664 of the saddle 656. The stem-like support 898 extends loosely through a hole (not shown) in said shelf-like part of the bracket 902 and is adapted to be so vertically adjusted by way of the clamping nuts 900 that the two follower rollers 896 straddle the guide rails 882 and 884. Thus, it will be apparent that as the entire slinger-supporting carriage assembly 530 revolves about the vertical axis $x-x$ of the turret 432, the rollers 896 will follow the closed arcuate path (circular or elliptical) which is defined by the upper open rim of the liner pattern 34, and the saddle 656 will move radially inwardly and outwardly in a reciprocating fashion, the amplitude of its reciprocation along the guide tube 642 being equal to one-half of the difference between the major axis and the minor axis of the ellipse when the upper open rim of the liner pattern is elliptical.

It is to be noted that the radial distances of the slinger discharge chute 46 and the rollers 896 from the vertical axis $x-x$ are such that with the rollers straddling the arcuate rails 882 and 884, the lower end of the chute is in register with the annulus 32 (see FIG. 2), this chute end lying just outside of the rails as the same sweeps around the upper rim of the liner pattern 34 in circumferential fashion. It is also to be noted that the turret turntable 562 constitutes the sole support for the slinger carriage 652 and its roller-supporting bracket 902 and, thus, no portion of the rim region of the pattern shell 36 is subjected to downward thrust by reason of the aforementioned roller-type rail follower.

The previously mentioned centering mechanism whereby the liner pattern 34 is caused to become centered within the ladle 10 during initial installation thereof is best illustrated in FIGS. 29 and 30 of the drawings and portions of this mechanism also are shown in FIGS. 2, and 25 to 28, inclusive. This mechanism is designated in its entirety by the reference numeral 910 and involves in its general organization a downwardly extending locating pin 912 (see FIG. 30) which is carried by the liner pattern 34, and a centering socket 914 which is established by the provision of a pilot tube 916. The latter is mounted on a spider-like frame structure which is positioned on the bottom wall 16 (see FIG. 2) of the ladle 10 in a manner that will be described in detail hereafter.

The pilot tube 916 is carried at the center of a series of quadrilaterally arranged radial arms 918 each of which is of two-part construction and consists of an inner tube section 920 which is square in cross section, 20 and an outer tube section 922 which is telescopically received in the inner section so as to be adjustable outwards and inwards in a radial direction. Longitudinal slots 923 (see FIGS. 29 and 32) in the upper portions of the inner tube sections 920 expose the inner end regions of the associated outer tube sections 922, and upstanding manipulating pins 924 are secured to the inner ends of the inner sections 922 and project upwardly through the slots 923. Vertically extending locking pins 926 (see FIG. 31) which are urged downwards by helical compression springs 928 cooperate with longitudinal series of closely spaced locating holes 930 in the upper outer portions of the inner tube sections 922 in order that the outer tube sections may be secured in any desired radial position with the inner tube sections. A rectangular reinforcing hub plate 932 overlies and is welded to the intersecting inner end regions of the four radial arms 918, the pilot tube 916 projecting upwardly through a hole 934 in the central portion of such plate.

The locating pin 912 is provided with a downwardly tapered lower end 936 and, as shown in FIGS. 25 to 29, inclusive, is carried on the central portion of a horizontal generally diametrically extending strut member 938. The latter is of a composite nature and includes two aligned channel members 940 which, at their inner end regions, are welded in back-to-back fashion to a third short channel member 942. The central portions of the horizontal flanges of the channel member 942 are burned out in order to receive the locating pin 912 which is welded in position in the burned out regions. 50 The outer ends of the two aligned channel members 940 are welded to attachment brackets 944 which, in turn, are welded to the walls 806 and 807 of the lower pattern section 802.

It is to be noted at this point that, although the radially extending, extensible and contractible arms 918 which are associated with the centering mechanism 910 and normally overlie on the bottom wall 16 of the ladle 10 are referred to herein as radial arms, in the illustrated form of the liner pattern 34, these arms are not truly radial since the point of divergency of these four arms is slightly offset from the geometrical center of said bottom wall 16 as clearly shown in FIG. 29. Similarly, although the horizontally extending strut member 938 which is carried on the lower pattern section 802 of the liner pattern 34 is referred to as being diametrically disposed with respect to such pattern section, actually this strut is slightly offset from a true di-

ameter and it, therefore, lies in a secant plane with respect to the liner pattern 34. These offset arrangements are necessary in order that the strut 938 shall be secured to only one of the two wall parts 806 and 807 so that it may move bodily with the part (807) to which it is attached when the liner pattern 34 as a whole is expanded and contracted as previously described.

The previously mentioned pattern levelling means which is carried at the lower end region of the lower pattern section 802 is provided for the purpose of adjusting the liner pattern 34 to a centered position within the ladle 10 at the time it is initially installed within the ladle. This means is comprised of a series of at least three, but preferably four, circumferentially spaced levelling jack assemblies 950, each of which includes an hydraulic jack proper 952 (see FIGS. 29 and 32) embodying a cylinder part 954 and a plunger part 956. The cylinder part of each assembly 950 is supported on a shelf-like bracket 958 which is welded to the inner side of one of the wall parts 806 or 807 as the case may be, and the plunger part projects downwardly and is adapted to seat on a reinforcing plate 960 which is interposed between the plunger and the bottom wall 16 of the ladle 10. Flexible hose connections 962 leading to the opposite ends of the cylinder parts 954 enable the various jack assemblies 950 to be individually operated from a remote region such, for example, as the control cabinet 722.

Still referring to FIGS. 29 and 33 of the drawings, the previously mentioned shield arrangement whereby the refractory lining material which is flung in wad form into the annulus 32 between the side walls of the ladle 10 and the liner pattern 34 is prevented from flowing or shifting inwardly beneath the pattern during ladle-lining operations consists of a pair of generally semi-cylindrical apron members 970 and 972 of short height, the apron member 970 closely hugging the lower portion of the inside wall surface of the wall part 806 of the lower pattern section 802, and the apron member 972 similarly hugging the lower portion of the inside wall surface of the wall 807. These apron members 970 and 972 are formed of sheet metal stock and are slidable vertically on the wall parts to which they are applied. Suitable notches 974, one of which appears in FIG. 33, are cut in the lower rims of the apron 970 and 972 in order to accommodate the outer ends of the outer tube sections 922 of the arms 918. At such time as ladle-lining operations have been completed and the liner pattern 34 is hoisted upwardly from the confines of the lined ladle, the top edge portions of the various notches 974 rest on the outer ends of said outer tube sections 922 so that the apron assembly will be lifted bodily with the liner pattern 34.

The above description of the ladle-lining apparatus which is illustrated in FIGS. 1 through 33 of the drawings is believed to be sufficiently detailed so that it is deemed unnecessary to enter into a comprehensive description of the operation of the apparatus throughout the entire lining of a ladle. A brief statement as to the movement or transfer of the lining material from its reception in dry batches at the dump bucket 60 of the skip hoist 38 to its delivery in a continuous stream into the receiving hopper 500 of the slinger assembly 44, a similarly brief statement in a continuous stream into the receiving hopper 500 of the slinger assembly 44, a similarly brief statement or discussion of the treatment of the lining material in and its discharge from the slinger

assembly, as well as entry of the material into the annulus 32 of the ladle 10 will suffice for substantially all of the automatic functions of the apparatus. Thereafter, a full discussion of the manual and power-hoisting operations that are conducted in connection with pattern placement and pattern removal should suffice for a full understanding of the operation of the entire apparatus.

The skip hoist 38, the mulling apparatus 40, the bucket elevator 50, and the feeder 52, all being conventional and commercially available items, it will be obvious that the batches of dry refractory lining material which are introduced from time to time into the dump bucket 60 of the skip hoist will be elevated and fed to the mulling apparatus where they are mixed with water in order to bring the pre-conditioned dry material to a properly moistened and conditioned plastic state which is suitable for ladle-lining purposes. This material is discharged from the feeder 52 into the receiving hopper 94 of the receiving conveyor 56. From the hopper 94, the prepared refractory lining material travels along the upper reach of the conveyor belt 142 of the receiving conveyor 56 and, at the distal end of this conveyor belt, it is discharged into the receiving hopper 294 of the delivery conveyor 58. It will be understood that because the two conveyors 56 and 58 are at all times in effective material-transfer communication with each other as previously described, the material which issues from the conveyor 56 will, regardless of the angular relationship between these two conveyors, be discharged into the hopper 294 which underlies the distal end of the receiving conveyor 56. There will, therefore, be no interruption in the constant feed of the prepared refractory material along the composite articulated conveyor assembly 54, because, as the slinger assembly 44 continues to orbit at a constant velocity about the rim of the liner pattern 34, the knee action joint which extends between the two conveyors 56 and 58 and is occasioned by the hinge assembly 308 will flex repeatedly, but there will be no loss of lining material in the transfer from one conveyor to the other. There will thus be a steady and continuous flow of the moist prepared refractory lining material to the slinger assembly 44.

It will, of course, be assumed that prior to initiating such a flow of material to the slinger assembly 44, the ladle 10 in which the pattern 34 has been operatively installed will be present in the pit 12. The ladle may be a stand-by ladle which has been awaiting the lining of a preceding ladle and has been hoisted into the pit from a stand-by location.

The procedure whereby the liner pattern 34 is initially installed in the pit-mounted ladle 10 will vary, depending upon the size and capacity of the ladle, as well as upon the equipment which is available for installing the pattern. As previously stated, the present ladle lining apparatus is primarily designed for use in the lining of large ladles. In a range of capacities extending up to two hundred and fifty tons or larger, depending upon hoisting facilities, it may be found desirable to handle the two split pattern sections 800 and 802, i.e., the upper and the lower sections separately. Ordinarily, a pattern which is designed for use with a small ladle will be handled bodily as a single unit, in which case the upper pattern section 800 and the lower pattern section 802 will be permanently bolted together, utilizing the clamping bolts 856 (see FIG. 23), as previously described for this purpose. After bolting the two pattern

sections together, the thus assembled liner pattern 34 may be hoisted by using the upper set of hoisting lugs 851. If successive hoisting operations are resorted to in order to install the liner pattern 34 within the ladle 10, the lower set of hoisting lugs 851 will be employed when initially setting the lower pattern section 802 into the ladle 10 and, thereafter, the upper set of hoisting lugs will be employed for placement of the pattern section 800 on top of the liner pattern section 802. In either instance, prior to placement of the lower pattern section 802 in the ladle, the workman will adjust the centering mechanism (see FIG. 29) so that the outer square tube sections 922 of the extensible and contractible radial arms 918 are fully extended into engagement with the ladle side wall 18 while the quadrilateral frame structure which embodies such arms rests on the bottom wall 16 of the ladle. The adjustment of these square outer tube sections will be made so that the centering socket 914 of the pilot tube 916 (see FIGS. 29 and 30) will attain the correct receiving position for reception therein of the center locating pin 912 which is carried by the channel 942 of the lower pattern section 802.

The lower pattern section 802 is then lowered into the ladle and coupling of the locating pin 912 and the pilot tube 916 is effected. As the lower portion of the lower pattern section 802 approaches the ladle bottom wall 16, the apron members 970 and 972 will be brought into engagement with said bottom wall 16, thus arresting further downward movement of these apron members. As the lower pattern section 802 continues to be lowered, the apron sections shift with respect to the wall parts 806 and 807 of the lower pattern section. After the lower pattern section 802 has become fully seated within the ladle, a workman who has descended into the lower section of the pattern 34 beneath the deck plates 844 and 846 will then retract the square tube sections so that they lie entirely within the confines of the generally cylindrical pattern section wall parts 806 and 807.

If the upper pattern section 800 has been bolted to the lower pattern section 802 for hoisting and lowering in unison therewith, the liner pattern 34 as a whole is at this time ready to receive thereon the ramming unit 45. If separate hoisting operations for the two pattern sections are resorted to, the upper pattern section 800 must be applied to the installed lower pattern section before the ramming unit can be installed. If such is the case, a workman inside the upper pattern section 800 will effect the necessary bolting operation after the latter section has been lowered into the ladle and brought to rest on the lower pattern section 802.

With both pattern sections bolted together and the thus assembled liner ladle 34 properly positioned within the ladle 10, the ramming unit 45 will be lowered into position over the upper pattern unit 800 so that the frame openings (see FIG. 17) 522 register with the tapered brackets 518 for guiding the undercarriage 504 of the ramming unit properly into position on the two deck plates 502 and 503. After the undercarriage seats on these deck plates, the hold-down plates 526 are installed as previously described in order fixedly to secure the ramming unit 45 in position on the liner pattern 34. Ramming operations may then take place with the prepared refractory lining material flowing to the orbiting slinger assembly 44 and the latter discharging

its wads of conditioned lining material into the annulus 32 as previously described in detail.

As previously stated, the wads of prepared refractory lining material issuing from the discharge chute 46 of the slinger assembly 44 possess unusual density by reason of the fact that the sand-compacting functions which take place within the impeller casing 750 are prolonged from the 6 o'clock position where the mass of material in the bottom region of the casing is initially engaged by the revolving cup-like blade unit 766 to the 9 o'clock position where the material, now compacted into wad form, is discharged. By reason of the carriage-adjusting screws 688 (see FIG. 12) the discharge chute 46 of the slinger assembly 44 is accurately "aimed" into the annulus 32 which exists between the side wall of the ladle 10 and the side wall or shell 36 of the liner pattern 34 to the end that these wads are directed downwardly alongside and in close proximity to the side wall of the liner pattern at precisely the same slant angle as that of such pattern side wall.

Upon filling of the annulus 32 with wads of the prepared refractory lining material, feeding operations are discontinued by causing all of the motors M1, M2, M3, M4, M5, M6 and M7 to become deenergized, thus terminating the rotation of the turret turntable 562. Then, prior to withdrawal of the liner pattern 34 from the lined ladle 10, the undercarriage 504 is released from the deck plates 502 and 503 by removing the hold-down plates 526, after which this undercarriage, as well as the entire ramming unit 45, may be hoisted from the lined ladle by causing the hoisting lugs 528 to be engaged by the lift hooks of an overhead crane or other hoisting mechanism.

After a given ladle has been rammed for lining purposes and the annulus 32 which exists between the side walls of the ladle and the liner pattern 34 is filled with densely rammed wads of prepared refractory lining material, the bond between the hardened lining material in the annulus and the outer surface of the side wall or shell 36 of the pattern 34 must be broken before the pattern can be hoisted from the lined ladle. To accomplish this, a workman who has descended the ladder 860 (see FIGS. 19 and 20) and a workman who has descended the ladder 864 will simultaneously manipulate the turnbuckle-type expansion and contraction jacks 824 in such manner as to swing the associated gate members 820 inwardly to their "open" positions as shown in FIGS. 17a. Immediately thereafter, these workmen will manipulate the pattern wall spreader jacks 830 in such a manner as to draw the clamshell-like wall parts 804 and 805, and 806 and 807 toward each other and, thus, effect contraction of the entire liner pattern 34 as a unit. During this contraction of the pattern, and as shown in FIG. 17a, the adjacent end regions of the two rails 884 and 886 will assume the overlapped condition in which they are illustrated in this view. With the pattern thus contracted or collapsed, the pattern may then be hoisted from the ladle, utilizing the upper group of apertured hoisting lugs 851 as anchor points for the lifting hooks of an overhead crane or the like.

In FIG. 34 of the drawings, a modified form of ladle-lining apparatus is shown. In such form of the invention, the basic pit-installation of the ladle 10 and its associated liner pattern 34 remains the same as the pit-installation of FIGS. 1 and 2. The basic turret turntable mounting for the slinger carriage 652 as well as the car-

riage itself remain unaltered. The slinger assembly 44 remains unchanged and its discharge chute 46 cooperates with the rim region of the liner pattern 34 and with the annulus 32 in the same manner as heretofore described in connection with the pit-installation of FIGS. 1 and 2. If the disclosure of FIG. 34 is compared with the disclosure of FIG. 2, it will be readily apparent that the only difference between the modified ladle-lining apparatus and the previously described apparatus resides in the provision of a fixed center-feed for the prepared refractory lining material undergoing continuous feeding to the slinger assembly 44 instead of the previously described peripheral feed which uses an articulated conveyor assembly having a flexible hinge joint or connection in its medial region.

Referring now to FIG. 34, and considering FIG. 12 for comparison purposes, the pit-installation, the ramming unit 45, including the slinger assembly and its turntable mounting means, are considered to be the same components or parts that are illustrated in FIG. 12 and, therefore, the same reference numerals are applied thereto in both of these figures.

Although the slinger assembly 44 in the modified center feed arrangement remains the same as in the peripheral feed arrangement, a different form of receiving hopper 1000 is used in place of the hopper 500. The hopper 1000 is of one-piece construction, but it will be understood that the lower end thereof communicates with the interior of the impeller casing 750 in the lower region thereof as in the case of the hopper 500 in order to attain the aforementioned 270° sand-impelling stroke of the cup-like blade unit from the point of lining material reception to the point of lining material discharge. The rim region of the hopper 1000 remains at all times in effective register with the discharge end of a radial center feed conveyor 1002 which is fixedly mounted on the ramming unit 45 by means of fixed mounting components including a pair of vertically extending, laterally spaced, triangular web-like brackets 1003 and a pair of upwardly and forwardly inclined brace bars 1004, as will be described in greater detail presently.

Structurally, the center feed conveyor 1002 is similar in many respects to the receiving conveyor 56 of FIG. 3 except for the disposition of the receiving hopper 94a which is associated therewith and, therefore, to avoid needless repetition of description, similar reference numerals with the suffix "a" have been applied to the corresponding parts thereof as between the disclosures of FIGS. 34 and 3. This center feed conveyor 1002 is fed with prepared refractory lining material by a supply conveyor 58a which is similar to the delivery conveyor 58 of FIG. 5 and which, accordingly, is designated by reference numerals of a similar character but with the suffix "a."

Still referring to FIG. 34, with FIGS. 3 and 12 being held for comparison therewith, the hopper 94a of the conveyor 1002 is maintained in approximate alignment with the vertical axis x—x of the casing 540 by way of bolts 1005 which are capable of selective reception in holes 1006 in the angle-pieces 180a of the conveyor frame 146a in order that said hopper 94a may be longitudinally adjusted with respect to said conveyor frame. The discharge end region of the center feed conveyor 1002 is identical with the discharge end region of the receiving conveyor 56 of FIG. 3, this region discharging the prepared refractory lining material into the modi-

fied receiving hopper 1000 which functions in the same manner as the hopper 500.

The end of the center feed conveyor 1002 which carries the drive pulley 140a also remains substantially the same as the receiving end of the conveyor 56 except for the fact that the transverse shaft 152a, instead of being supported by a gear reduction casing, is supported by the aforementioned brackets 1003, and the latter are, in turn, supported by an upright frame structure 1008 which is held in position by the clamping nuts 694. The aforementioned brace bars 1004 which support the discharge region of the conveyor frame 146a extend between the side bars 150a of said conveyor frame 146a and the side webs 716 of the ramming unit 45.

15 The discharge end of the supply conveyor 58a remains substantially the same as the discharge end of the delivery conveyor 58 with the exception that the frame extension 389 (see FIG. 5) and the height-adjusting means 381 on such extension are omitted inasmuch as the discharge end of the conveyor is otherwise supported.

20 Since, for descriptive purposes herein, the ramming unit 45 of FIG. 34 is considered to be, in fact, the same ramming unit as that shown in FIG. 12, regardless of 25 whether it be used in the peripheral feed apparatus which is described in connection with FIGS. 1 through 33 or the center feed apparatus of FIG. 34, its operation remains precisely the same in both cases. The only difference between the two apparatuses resides in the 30 manner in which the prepared refractory lining material is conducted from the bucket elevator 50 (see FIG. 2) or other source of lining material to the ramming units which are associated with the two apparatuses. Either ladle-lining apparatus may possess an advantage 35 over the other apparatus, depending upon the particular environment of the apparatus as, for example, the available floor space or the proximity of extraneous steel mill equipment to the bucket elevator or to the ladle pit 12. With either apparatus, ladle-lining procedures remain precisely the same.

40 Steel mill ladles of the type under consideration vary in their dimensions both as regards the shape of their rims and the shape of their bottom walls. Some ladles have slightly elliptical rims, which is to say that the rims 45 thereof are possessed of major and minor axes which differ by as much as twenty-four inches, depending upon the size and capacity of a particular ladle. Most ladles also have circular bottom walls although a few 50 have elliptical bottom walls. Nearly all ladles have side walls which slant inwardly and downwardly in order to accommodate a transition from the shape of their rims to the shape of their bottom walls. Therefore, strictly speaking, a given ladle cannot be said to be truly frustoconical. Where a given ladle is provided with a truly circular rim, there is a question as to whether, in seeking a generic definition, the term "elliptical" would be 55 applicable to such a rim even though a circle is a special form of ellipse which occurs when the two axes of the ellipse attain equality. Therefore, in order to make it clear that the present invention is intended to cover the lining of all manner of steel mill ladles, whether their rims and bottom walls are elliptical or circular and whether their side walls are truly frusto-conical or deviate slightly from a cone frustum or are cylindrical, it 60 will be understood that the term "elliptical" is intended to cover a circular shape; that the term "frustoconical" is intended to cover a structure which gives

the general appearance of a cone frustum but which, in reality, deviates therefrom at various levels and in which its slant height may vary at different circumferential surface regions; and that minor departures in shape as, for example, an outstruck pouring lip on the rim of a ladle, shall not nullify a term which is used to designate an over-all contour in the absence of such departure.

The invention is not to be limited to the exact arrangement of parts shown in the accompanying drawings or described in this specification as various changes in the details of construction may be resorted to without departing from the spirit or scope of the invention. For example, although the present ladle-lining apparatus has been shown and described in connection with the lining of a pit-mounted ladle, it is obvious that, if desired, a mobile carriage-mounted ladle which travels on rails is capable of being lined in situ when brought to the vicinity of a ramming unit such as the unit 45 at a ramming station. Therefore, only insofar as the invention is particularly pointed out in the accompanying claims is the same to be limited.

Having thus described the invention what we claim as new and desire to secure by letters patent is:

1. An apparatus adapted for use in lining the downwardly and inwardly slanting side wall of a relatively deep upright metallurgical vessel having a generally circular bottom wall and an open elliptical rim, said apparatus comprising a shell-like pattern removably mounted within said vessel in substantially coaxial relationship and, in combination with said side wall, defining a material-receiving annulus, a ramming unit removably mounted on and supported by said pattern for ramming said annulus with wads of refractory lining material, said pattern constituting the sole support for said ramming unit, said ramming unit including a turntable mounted for rotation about the axis of the ladle and pattern, a slinger carriage eccentrically mounted on said turntable for orbital movement about said axis and freely movable in a radial direction with respect thereto throughout a limited range of radial movement, a slinger assembly mounted on said carriage and having a discharge chute in register with said annulus and adapted to project wads of lining material into the latter in order progressively to fill the same, cooperating guide means on said carriage and pattern constraining the carriage during its orbital movement to travel in an elliptical path conformable to contour of said rim and thus maintain the discharge chute of said slinger assembly in effective register with the annulus, means for rotating said turntable, and means for continuously supplying lining material to said slinger assembly during orbital movement of said carriage.

2. An apparatus as set forth in claim 1 and wherein said guide means comprises an elliptical guide rail carried and supported by by said pattern and a rail follower effectively mounted on said slinger assembly.

3. An apparatus as set forth in claim 1 and wherein said pattern is in the form of a hollow open-ended shell conformable in configuration to the inside surface of the ladle side wall to be lined and presenting an upper rim part, and said guide means embodies a steel ring removably seated on said rim part and coextensive therewith, and a pair of follower rollers effectively carried by said slinger assembly and between which said steel ring projects.

4. An apparatus as set forth in claim 3 and wherein said rim part is in the form of an elliptical ring which is removably seated on and secured to the upper end of said pattern shell pilot lugs are secured to the inside face of said rim part in circumferentially spaced relationship, said pilot lugs projecting upwardly beyond such rim part and, collectively, serving to center the steel ring relative to the axis of the pattern and maintain the same seated on said rim part.

5. An apparatus as set forth in claim 1 and wherein said including additionally means for varying the eccentricity of said limited range of movement within which the slinger carriage is freely movable, said means comprising a radially shiftable carriage support on said turntable and on which the slinger carriage is slidably mounted, and adjusting means whereby the radial position of said carriage support may be varied.

6. An apparatus as set forth in claim 5 and wherein the turntable is provided with a centrally positioned guide bracket, the radially shiftable carriage support is in the form of a guide tube slidable in said bracket, and the adjusting means for varying the eccentricity of said limited range of carriage movement comprises a plurality of threaded adjustment rods which are effective between fixed regions on the turntable and guide tube respectively.

7. An apparatus as set forth in claim 6 and wherein said shell-like pattern includes an outer shell wall of inverted frusto-conical configuration and of a slant angle conformable to the slant angle of said inwardly slanting side wall of the ladle, and the cooperating guide means on the carriage and pattern comprises an elliptical guide rail removably seated on the upper rim of said pattern shell wall, and a pair of follower rollers mounted on said slinger carriage and between which said guide rail projects.

8. A ladle-lining installation comprising a relatively deep upright ladle having a generally circular bottom wall from which there projects upwardly an inverted frusto-conical side wall terminating in an open upper elliptical rim, a shell-like pattern having an outer inverted frusto-conical side wall terminating in an open upper elliptical rim conformable in contour to that of the rim of the ladle, said pattern being disposed within said ladle in coaxial relationship so that said side walls establish therebetween an annulus of substantially uniform radial thickness, a deck plate projecting across the upper end region of said pattern shell, a ramming unit removably mounted on said deck plate for ramming said annulus with wads of refractory lining material, said ramming unit comprising an undercarriage seated on said deck plate, a pedestal-like casing projecting upwardly from said undercarriage, a turntable mounted on said casing for rotation about the axis of the pattern, a guide sleeve centrally mounted on the turntable, a guide tube slidable in said sleeve and radially extensible therefrom, means for securing said guide tube in a selected extended position, a slinger carriage slidably mounted on the outer end region of said guide tube for free limited axial sliding movement thereon and for orbital movement about the axis of the pedestal-like casing and turntable, a slinger assembly mounted on said carriage and including a slinger proper having an impeller casing, a discharge chute in communication with said impeller casing and in register with said annulus for discharging wads of lining material thereinto, and an electric motor fixedly secured

to said impeller casing for actuating the slinger proper, a pair of trunnions carried by said motor and rotatably supported on the carriage, said trunnions constituting a pivotal support for the slinger assembly as a whole whereby the slant angle of the discharge chute may be varied, means for securing said motor in a selected position of adjustment to conform the slant angle of the discharge chute to that of the pattern shell side wall, and means for rotating said turntable.

9. A ladle-lining installation as set forth in claim 8 and wherein said guide tube serves at its outer end fixedly to support a saddle member having upstanding end flanges which serve to support therebetween a pair of parallel guide rods on opposite sides of said guide tube, and the slinger carriage is provided with a pair of guide sleeves which are freely slidable on said guide rods.

10. A ladle-lining installation as set forth in claim 9 and wherein each guide rod is surrounded with a flexible protective bellows-like boot on each side of its associated guide sleeve, said boots being axially extensible and contractible in conformity with the sliding of said sleeves on said guide rods.

11. A ladle-lining installation as set forth in claim 8 and wherein said means for rotating the turntable comprises an electric turntable motor effectively mounted on said undercarriage, a gear reduction device likewise effectively mounted on the undercarriage and connected to the motor in driven relationship, said gear reduction device having an output shaft, a pinion on said output shaft, and a ring gear secured to the turret in concentric relationship and meshing with said pinion.

12. A ladle-lining installation as set forth in claim 11 and wherein said turntable motor is mounted on a shiftable motor platform which is slidable on said undercarriage and is drivingly connected to the gear reduction device by a variable speed spring-loaded split pulley device, and worm and sleeve means are provided for shifting the position of said motor platform in order to change the speed ratio of said variable speed device.

13. A ladle-lining installation as set forth in claim 11 and including, additionally, a plurality of circumferentially spaced post-like tapered locating brackets mounted on said deck plate and projecting upwardly therefrom, said undercarriage being provided with a series of correspondingly located openings therein into which the locating brackets project, said brackets and openings serving to facilitate lowering of the ramming unit into a centered position on the pattern.

14. A ladle-lining installation as set forth in claim 11 and wherein said undercarriage is in the form of a plurality of structural steel members secured together and forming a right angle cross which seats upon said deck plate and embodies two aligned radial arms which extend in the direction of the major axis of the elliptical rim of the pattern side wall, and two aligned radial arms which extend in the direction of the minor axis of said elliptical rim.

15. A ladle-lining installation comprising an upright ladle having a generally circular bottom wall from which there projects upwardly an inverted frustoconical side wall terminating in an open upper rim, a pattern removably mounted within said ladle in substantially coaxial relationship and, in combination with said side wall, defining an annulus for receiving refractory lining material, a turntable mounted on said pattern for rotation about the vertical axis of the pattern,

a slinger assembly eccentrically carried by said turntable for orbital movement about said axis, having a discharge chute in register with the annulus, and adapted to project wads of lining material into said annulus, said slinger assembly further including a material-receiving hopper, a material feeder means remote from said ladle and having a continuous material discharge, and conveyor means for continuously conducting lining material from said feeder means to said receiving hopper,

10 said conveyor means comprising a first material-receiving conveyor of the belt and pulley type and including a frame mounted at its proximate receiving end for swinging movement in a horizontal plane about the axis of said continuous material discharge, a second material-delivery conveyor of the belt and pulley type and including a frame hingedly connected at its proximate receiving end to the distal discharge end of the first conveyor frame for swinging movement in a horizontal plane, the proximate receiving end of the second conveyor frame being in effective material-receiving communication with the distal discharge end of the first conveyor frame, said material-receiving hopper underlying the distal discharge end of the second conveyor frame in material-receiving relationship, and a rotary hinge connection effective between said hopper and said discharge end of the second conveyor frame to transmit the orbital movement of the slinger assembly to the discharge end of said latter conveyor.

16. A ladle-lining installation as set forth in claim 15 and wherein said hinge connection comprises a pilot socket member mounted on said hopper and a cooperating pilot stem mounted on said second conveyor frame.

17. A ladle-lining installation as set forth in claim 16 and wherein said hopper is provided with a funnel-like rim region, the socket member is in the form of a transversely extending strut which projects substantially diametrically across said rim region below the level of the rim proper and is provided with a socket in the central region thereof, and the pilot stem projects vertically downwardly from the distal end of the second conveyor frame and has its lower end extending into and seated within said socket.

18. A ladle-lining installation as set forth in claim 17 and wherein means are provided for varying the effective length of the pilot stem to vary the height of the discharge end of the second conveyor frame with respect to said hopper.

19. A ladle-lining installation as set forth in claim 18 and wherein said means for varying the effective length of the pilot stem comprises a threaded portion which is formed on the pilot stem and projects through an opening in the distal end of the second conveyor frame, and a pair of clamping nuts on said threaded portion on opposite sides of the frame opening.

20. A ladle-lining installation as set forth in claim 19 and wherein said opening in the distal end of the second conveyor frame threadedly receives said pilot stem therethrough, and the pilot stem is provided with a crank arm by means of which it may be manipulated.

21. An apparatus adapted for use in lining the downwardly and inwardly slanting side wall of a relatively deep upright metallurgical vessel having a generally circular bottom wall provided with a stopper hole therein, and an open elliptical rim, said apparatus comprising a shell-like pattern removably mounted within said vessel in substantially coaxial relationship and, in combina-

tion with said side wall, defining an annulus for reception of refractory lining material, a ramming unit removably mounted on said pattern for ramming said annulus with wads of the refractory material, said ramming unit including a pedestal-like casing mounted on the central portion of the upper portion of the pattern, a turntable mounted on the casing and adapted for rotation about the axis of the ladle and pattern, a slinger carriage mounted on said turntable for orbital movement about said axis and freely movable in a radial direction with respect thereto, a slinger assembly mounted on said carriage and having a discharge chute in register with said annulus and adapted to project wads of lining material into the latter in order progressively to fill the same, cooperating guide means on said carriage and pattern constraining the carriage during

orbital movement to travel in an elliptical path conformable to the contour of said rim and thus maintain said discharge chute in register with the annulus, an electric turntable motor mounted on said pattern and connected to the turntable in driving relationship, an electric slinger assembly motor fixedly mounted on the slinger assembly in driving relationship, a series of collector rings disposed within said casing and electrically connected to said slinger motor, and a lead-in power supply cable for said turntable and slinger motors having electrical connections extending to said collector rings and turntable motor respectively, said power supply cable extending from a source of electrical current and passing through said stopper hole.
